CODED TRACK CIRCUIT SIGNALING
SYSTEMNeil D. Preston, Rochester, N. Y., assignor to
General Railway Signal Company, Rochester,
N. Y.

Application September 29, 1942, Serial No. 460,106

40 Claims. (Cl. 246—33)

This invention relates to coded track circuit signaling systems for railways, and more particularly to an automatic block signaling system for single track railroads.

In one type of automatic block signaling system for single track railroads, commonly known as the absolute-permissive-block or A. P. B. system, the signals governing train movement into and through each single track stretch between passing sidings are normally clear to permit trains to enter the stretch at either end in accordance with train orders or time table rights. When a train enters a single track stretch, the opposing signals are automatically put to stop by an operation conveniently termed a tumble-down control; and as the train travels through the stretch and passes each intermediate signal, a directional means is conditioned to permit clearing of the signals for following train movements independently of the tumble-down control. In addition to this tumble-down and directional control for the signals of the single track stretch, the entering signals governing train movement into a passing siding and its associated siding section, and each of the intermediate signals in the rear of these entering signals, are governed in a special way to provide what is commonly known as a double distant and siding overlap control in the manner and for the purposes familiar to those skilled in the art.

The primary object of the present invention is to provide an automatic block signal system for single track railroads of the absolute-permissive-block type which is operated by the coded track circuits without any line wires between signal locations, and which affords all of the signaling protection for opposing and following train movements characteristic of the well-known A. P. B. system using conventional track circuits and line wires.

In the conventional coded track circuit, the track rails at one end of a track section are intermittently energized to form code pulses for operating a code following track relay at the other end of the track section, unless a track section is occupied by a train; and by changing the rate or periodicity of these code pulses, or otherwise varying their code character, distinctive controls may be transmitted over the track rails for governing the indication of wayside or cab signals without the use of line wires.

In applying such coded track circuits to an automatic block signaling system of the A. P. B. type, it becomes necessary to provide for suitable code control over the track rails of the track sec-

tions in both directions to provide for clearing the starting or head-block signals at both ends of the single track stretch when this stretch is not occupied, thereby allowing a train to enter the stretch at either end under a clear signal when traffic conditions permit, and also provide for a tumble-down control for both directions to put to stop opposing signals when a train enters the stretch. This desired code control for both directions in the track sections of a single track stretch under normal conditions may be obtained by using a driven code for one direction and an inverse or off-code for the opposite direction, as disclosed in my prior application, Ser. No. 413,021, filed September 30, 1941. Also, a code control in both directions in a track section for detection of occupancy and tumble-down control may be obtained by applying what may be termed the beat code principle as disclosed, for example, in connection with a coded track circuit signaling system having supervisory manual control, in the prior application of Judge, Ser. No. 455,922 filed Aug. 24, 1942.

In accordance with the present invention, it is proposed to employ the beat code principle disclosed in this Judge application, Ser. No. 455,922, rather than driven and inverse codes disclosed in my prior application, Ser. No. 413,021, for the control of the signals in an automatic A. P. B. system; and although the present invention involves functions and structural organizations similar to those disclosed in these prior applications, no claim is made herein to any of the features disclosed in these prior applications.

Generally speaking, and without attempting to define the nature and scope of this invention, each track section is equipped with a code transmitting means including coding contacts operated by a code oscillator or equivalent coder device; and under normal conditions these transmitting means for the opposite ends of the same track section are governed by coding contacts operated at different rates, such as 75 and 120 times per minute, thereby providing beat code pulses alternately in opposite directions over the track rails of the track section to cause intermittent energization of the code following track relays at both ends of that track section. Such intermittent energization of the track relays by beat code pulses may be utilized to detect occupancy and provide tumble-down control, since the energization of a track relay will cease if the track section becomes occupied, or if the opposing code pulses are cut off by a tumble-down control from an adjacent track section; but such intermittent

energization of a track relay is not at a distinctive code rate suitable for governing the clear indication of a signal, as distinctive from its caution indication, as required for the head-block signals in an automatic A. P. B. system. Accordingly, in the present invention, special provision is made for obtaining a clear indication of the head-block signals under beat code conditions by cancelling or suppressing the beat code conditions until code pulses at a predetermined clear code rate have been received at a head-block signal without interference, and cause that signal to indicate clear, whereupon the opposing code pulses at the appropriate different rate are applied to establish beat code conditions, and the clear indication of the signal once established is then maintained so long as code pulses are being received at that signal regardless of their particular rate.

Stated more specifically, the system of this invention employs a distant relay for each head-block signal, which is energized by an associated decoding means only when the corresponding code following track relay is intermittently energized at a predetermined clear code rate, such as 120 code pulses per minute; and this distant relay when once energized causes the application of code pulses to create a beat code condition, and is maintained energized by a stick circuit or equivalent means so long as the associated home relay is energized by an intermittent operation of the corresponding track relay at recurrent intervals under the beat code conditions. Under other conditions, when both the distant relay and the home relay are deenergized by the tumble-down control due to the presence of a train in a stretch moving toward the head-block signal, code pulses at a code rate determined by traffic conditions are supplied for governing the indication of the intermediate signal governing train movement toward said head-block signal.

In the present invention, this same beat code principle is also employed with special control, in the manner similar to that disclosed in my prior application, Ser. No. 413,021 above mentioned, to provide without use of line wires the double distant and siding overlap control characteristic of the A. P. B. system.

Another object of this invention is to provide suitable automatic control of a switch lock for an outlying switch so as to prevent this switch from being unlocked and operated while a train is approaching in either direction, and still permit the switch to be unlocked and operated with facility for a train movement from the main track over the switch.

Inasmuch as most railroads have highway crossings at grade level, it is another object of the present invention to provide a novel and simple means for controlling highway crossing signals automatically upon the approach of a train in either direction over single track stretches in such a manner as to readily effect the stopping of the highway crossing signal in its warning operation as soon as a train passes such highway. Although one purpose of the invention is to provide such highway crossing protection which is particularly suitable to the signaling system disclosed herein, it is also an object of the invention to provide such automatic highway crossing control in a manner which is also adaptable to various other coded track circuit signaling systems.

Various other objects, characteristic features and attributes of the invention will be pointed out, and also become apparent, as the specific embodiments of the invention are hereinafter described and explained; and the combinations of

functions and structural organizations constituting the invention will be set forth in the appended claims.

In describing the invention in detail, reference 5 will be made to the accompanying drawings, in which certain specific embodiments of the invention have been illustrated in a simplified and diagrammatic manner, more with the object of facilitating an explanation and understanding of 10 the nature and mode of operation of the system, rather than to show in detail the construction and arrangement of parts preferably employed in practice. These drawings comprise a number of figures as follows:

15 Figs. 1A, 1B, 1C and 1D, adapted to be arranged end to end, illustrate one embodiment of the invention of this system as applied to a typical stretch of single track between the ends of passing sidings, and as applied to a typical one passing siding and associated siding track section when 20 Figs. 1D and 1A are placed end to end in that order;

25 Figs. 2A to 2V (letter I omitted) inclusive constitute a series of explanatory diagrams illustrating the conditions of coding in the several 30 track sections and the control of the signals for certain typical train movements;

35 Figs. 3A and 3B illustrate a modified arrangement of the control circuits for governing the intermediate signals associated with the middle track section of a single track stretch;

40 Figs. 4 and 5 show conventionally and diagrammatically different specific embodiments of the automatic control of a switch lock for an outlying switch in accordance with this invention;

45 Figs. 6A, 6B and 6C, placed end to end, show conventionally and diagrammatically one specific embodiment of a highway crossing control system of the type particularly adapted for use with the coded track circuit automatic APB system of this invention;

50 Figs. 7A to 7F inclusive constitute a series of explanatory diagrams illustrating different conditions of coding for certain typical train movements past the highway crossing of Figs. 6A, 6B and 6C; and

55 Fig. 8 is a diagrammatic illustration of the manner in which "beat code impulses" are formed by the combination of two independently operable coders operating at different rates and located at the opposite ends of the track section 1—4T of Figs. 1A-1B.

60 The various relays, contacts and other parts have been illustrated in these drawings in a conventional manner; and to simplify the illustration of the circuits, connections to the opposite terminals of the battery or other suitable source of current for energizing the local circuits have been represented by the symbols (+) and (—) 65 associated with arrows. A system of this type inherently involves a similarity and duplication of relays and like parts for the different signal locations; and for simplicity various relays common to the various signal locations are assigned the same reference letter with a prefix numeral corresponding to the signal. In many instances, the same arrangement of control circuits is employed for energizing corresponding relays associated with the different signal locations, so that 70 a description of the circuits and mode of operation for one typical signal location applies to all signal locations; and while there are corresponding contacts in many cases at the different signal locations, these contacts will be designated by 75 different reference numbers in order as the oper-

ation is described for certain typical train movements.

General organization.—For the specific embodiments in the invention illustrated, it has been assumed that the invention is applied to a typical single track railway comprising stretches of single track divided into a plurality of track sections between the ends of passing sidings, together with passing sidings and associated siding track sections constituting the portion of the main track opposite these passing sidings. It has also been assumed that the passing sidings are not equipped with track circuits. The switches AW and BW at the ends of the passing sidings are arranged to be operated manually by the train crew in accordance with the usual practice; and it is assumed that the switches will be equipped with suitable switch circuit controllers (not shown) for governing the coded track circuits and signals in accordance with the usual practice.

Figs. 1A to 1D inclusive, when arranged end to end, illustrate the apparatus and circuits for a single track stretch between siding ends A and B, with starting or head-block signals 1 and 8 governing east-bound and west-bound train movement respectively into the stretch, entering signals 2 and 7 governing west-bound and east-bound train movement respectively out of the stretch into their corresponding passing siding or associated siding track section, and two pairs of opposite intermediate signals 3, 4 and 5, 6 governing train movements in the opposite directions through the stretch. These signals may be of any suitable type, but for simplicity in the illustration of their control circuits, these signals are assumed to be color-light signals which display green, yellow and red lights for clear, caution and stop indications when the lamps G, Y and R are lighted by the circuits shown. In accordance with usual practice, the head-block signals 1 and 8 are arranged to display an absolute stop-and-stay indication, while the other signals are arranged to display permissive stop indications, such as by the vertical or staggered relation of the signal light with a marker light (not shown).

In the particular arrangement shown, provision is made for approach lighting the entering signals and intermediate signals; and if the passing sidings are provided with track circuits, the head-block signals may also be approach lighted, instead of normally lighted as shown. The indications of these signals are governed by home relays H and distant relays D; and it is evident that these two relays may be employed in accordance with established practice for governing semaphore signals, or other types of color light signals, such as the so-called search-light signal disclosed in the patent to Field, No. 2,097,785, November 2, 1937.

Each of the siding track sections opposite a passing siding and each track section or block between successive signals is provided with coded track circuit equipment similar to, and involving the same operating principles as the conventional and well-known coded track circuit. This coding equipment is substantially the same for each end of each track section, and comprises a source of current (assumed to be a battery), a code following track relay TR, a code transmitter relay CTP, and coding contacts intermittently operated at predetermined code rates by a code oscillator or equivalent power operated device, these coding contacts being designated 75CT, 120CT and 180CT corresponding with code rates of 75, 120 and 180 times per minute selected as

suitable for this invention, although it should be understood that other specific code rates may be employed. Each code transmitter relay CTP is arranged to be operatively connected under the various traffic conditions to appropriate coding contacts; and when this transmitter relay is energized and deenergized it connects the source of current and the track relay respectively across the track rails alternately at a rate determined by the coding contacts to which the transmitter relay is then connected.

Each track relay TR governs the energization of a decoding transformer in the usual way to cause the energization of a home signal control relay H while the track relay is intermittently energized at recurrent intervals, regardless of the particular rate of such intermittent energization. This decoding transformer also governs the energization of a distant signal control relay D by a tuned circuit and rectifier, so that this distant relay D is energized in response to the coding operation of the track relay TR at a predetermined clear code rate, all in a manner that will be readily apparent to those skilled in the art without further explanation.

In the specific embodiment of the invention shown in Figs. 1A to 1D, inclusive, the 75 code rate is used for the caution signal indication and the 120 code rate for the clear signal indication, except in the case of entering signal 7 (see Fig. 1D) where the clear indication is given when the distant relay 1D is energized by a code of the 180 code rate, and the caution indication either by a 75 code energizing the home relay 1H alone, or 120 code energizing a special distant signal control relay 1DX as well as the home relay 1H. This caution control of the entering signal 7 by different 75 and 120 code rates is employed in connection with the control for a conditional double distant indication in the manner later explained.

Each of the code following track relays TR, although illustrated conventionally as a neutral relay, is preferably of the two-position biased polar type and responsive to one polarity of energization only as indicated by arrows; and the polarities to which these track relays will respond and the polarities of the track batteries are chosen for the several track sections so that each track relay is not operable by its associated track battery, nor by the track battery on the opposite side of the associated insulated joints. In other words, the polarities are preferably staggered in a well-known manner to provide broken down joint protection. Similarly, the code transmitter relays CTP are preferably of the two-position biased polar type for quick operation, while the other relays of the system are of the usual neutral type, some equipped with copper slugs or shunting rectifiers so as to have the desired slow-release characteristics.

Also associated with each signal, except the entering signals 2 and 7, is a series or approach lighting track relay SR, its slow-release repeater relay SRP, and a directional stick relay S. The series relay SR is connected in series with the track battery and adapted to be intermittently energized when the corresponding transmitter relay CTP is energized while the corresponding track section is occupied by a train, due to the increase of current through this series relay SR caused by the wheel shunt of the train. The series repeater relay SRP is sufficiently slow-releasing to hold its contacts closed although its series relay SR is intermittently energized. Each

of the directional stick relays S is arranged to be energized by circuits later explained only if a train moves in the direction of traffic governed by the associated signal, and is maintained energized so long as such train occupies the track section in advance of said signal.

It has been assumed that the coded track circuits will be of the conventional direct current type using primary batteries, or storage batteries trickle-charged from a suitable power line in accordance with common practice; but it should be appreciated that the same features and operating principles of the invention may be used in connection with coded track circuits energized by alternating current, or a half-wave of alternating current, or in any other suitable manner.

Other features of the system are more conveniently discussed in connection with the following description of the operation for certain typical train movements.

Normal conditions.—The parts and circuits are shown in the drawings in the normal condition existing when no trains are present, except perhaps on a passing siding having no track circuit.

Under these normal conditions, code pulses (conveniently termed beat code pulses) are being transmitted in both directions in each track section to energize intermittently both of the track relays for that track section. Generally speaking, this beat code condition is produced by governing the transmitter relays CTP for the opposite ends of the same track section by coding contacts operating at different code rates, such as 75 and 120 times per minute, each transmitter relay being preferably arranged to be energized upon closure of its associated coding contacts only if the corresponding track relay TR is then deenergized. In the case of the end track sections 1—4T and 5—8T in Figs. 1A and 1D, the transmitter relays 4CTP and 5CTP providing code pulses and operating the track relays 1TR and 8TR, associated with the corresponding head-block signals 1 and 8, are normally governed by coding contacts 120CT operating at the clear code rate, while the transmitter relays 1CTP and 8CTP at the opposite ends of these end track sections are normally governed by coding contacts 75CT operating at the caution code rate. In this instance, the selection of the direction for the transmission of code pulses at the higher code rate is necessary to provide the required clear indications of the head-block signals 1 and 8; but the selection of direction for transmitting code pulses at the higher code rate in the other track sections is a matter of arbitrary choice. In the arrangement shown, as a matter of choice, the higher 120 code rate is used for transmission of code pulses west in the siding track section 1—2T and in the middle track section 3—6T. The direction of the beat code pulses and the rate of their governing coding contacts is indicated in the diagram of Fig. 2A, the dotted line arrows being used to distinguish beat codes from driven codes indicated by solid arrows in the diagrams of other figures, such as Fig. 2B. It is to be understood that the actual rate of the beat code pulses in any track section is a combination of the two different rates of the governing coding contacts at the opposite ends of that track section and the resulting rate has not been indicated in the diagram of Fig. 2A.

Considering now more in detail the so-called beat code conditions in a track section, and referring to the track section 1—4T in Figs. 1A and 1B as typical, and further disregarding for

the present how these normal conditions became established, the transmitter relay 1CTP (Fig. 1A) is connected to coding contacts 75CT by a circuit which may be traced from (+), through a back contact 20 of track relay 1TR, coding contacts 75CT, front contact 21 of the distant relay 1D, transmitter relay 1CTP, and back contact 22 of the directional stick relay 1S, to (-). The transmitter relay 4CTP for the other end of this track section (Fig. 1B) is connected to coding contacts 120CT by a similar circuit from (+), through a back contact 23 of the track relay 4TR, coding contacts 120CT, front contact 24 of home relay 3H, transmitter relay 4CTP, and back contact 25 of directional stick relay 4S.

Thus, the transmitter relays 1CTP and 4CTP for the opposite ends of this track section 1—4T are energized from coding contacts operating at different code rates subject to the deenergized condition of the corresponding track relay; and the net effect is to provide code pulses of slightly variable duration and time spacing alternately in opposite directions, as shown by the diagrams of Fig. 8. For example, if the coding contacts 75CT governing the transmitter relay 1CTP are closed at a given instant while the coding contacts 120CT governing the other transmitter relay 4CTP are open, so that the track relay 1TR is deenergized, then at this instant the transmitter relay 1CTP becomes energized and applies the track battery to the corresponding end of the track section and energizes the track relay 4TR at the other end; and when this code pulse ceases, the transmitter relay 4CTP at said other end may be energized to apply a battery at that end to energize the track relay 1TR. Since the coding contacts governing these transmitter relays are operated at different rates, they act to close the energizing circuits for these transmitter relays at different intervals and tend to provide code pulses at these different intervals in opposite directions.

In the preferred arrangement shown, each transmitter relay cannot be energized, regardless of the closure of its associated coding contacts, until the code pulse from the opposite end of the track section ceases, and its associated track relay becomes deenergized. Consequently, a transmitter relay CTP cannot operate to disconnect its track relay from the track rails and cut short its energization by a code pulse being applied at the opposite end of the track section. In other words, the energization of a track relay initiated during the "off" period of the associated coding contacts is maintained for the full duration of the code pulse from the opposite end, and is not unduly curtailed by a subsequent closure of its associated coding contacts. Thus, although intermittent energization of both of the track relays of a track section can be produced by transmitter relays governed directly by coding contacts operating at different code rates independently of the energized condition of the corresponding track relay, and may be used with this invention if desired, the control of each transmitter relay by the back contact of its associated track relay in the manner shown is preferred, because it serves to provide track relay energizations of more uniform duration.

Another important aspect of the control of each transmitter relay CTP by the back contact of its associated track relay TR is the protection afforded against false self-coding operation in the event of foreign current on the track rails. Suppose, for example, that a stray potential ex-

ists for some reason across the track rails of the track section 1-4T of a polarity and intensity sufficient to operate the track relay 1TR. Under these conditions, and without the control of transmitter 1CTP by the back contact 20 of the track relay 1TR as shown, it can be seen that while the transmitter relay 1CTP is operating, the track relay 1TR is alternately disconnected and connected with the stray potential and is thus coded at the code rate of the operation of this transmitter relay 1CTP in spite of the absence of legitimate code pulses by tumble-down control, thereby tending to cause signal 1 to display a false indication. In the arrangement shown, when track relay 1TR is once energized by a stray potential, it opens its back contact 20 and prevents any further operation of the transmitter relay 1CTP, and leaves this track relay 1TR steadily energized by the stray current. In short, the back contact 20 of the track relay 1TR protects against false coding operation by foreign current as well as improves the performance of the track relays under beat code conditions.

In this connection, in the interests of saving contacts on the track relay 1TR, or the use of a repeater track relay, the back contact 20 supplying current to the energizing circuit for the transmitter relay such as 1CTP also supplies current to the lower half of the primary winding of the decoding transformer; and it can be appreciated that if the mid-tap connection for this primary should be broken, the transmitter 1CTP may be energized in series with this primary through the front contact 20 of the track relay 1TR. Under such conditions, however, there is no energization of the primary of the decoding transformer when back contact 20 is closed, and the current flow through both sections of the primary winding of the decoding transformer in series with relay 1CTP is insufficient to cause an operating energization of the relays 1H and 1D, and hence no improper operation of the corresponding home relay 1H or distant relay 1D occurs. On the other hand, separate contacts may be provided on the track relay for the two different functions of controlling the decoding transformer and the back contact check in the transmitting relay circuit, if desired.

Beat code conditions similar to those just described for the track section 1-4 exist in each of the track sections; and while the control circuits involved are similar, there are certain detail differences in the specific circuits for the various transmitter relays CTP, so that it is expedient to point out each of these circuits.

Referring to Fig. 1B, the energizing circuit for the code transmitting relay 3CTP is closed under normal conditions from (+), through a circuit including back contact 26 of track relay 3TR, coding contacts 75CT, front contact 27 of the distant relay 3D, front contact 28 of the home relay 4H, transmitting relay 3CTP, back contact 29 of directional stick relay 3S, to (-). Thus, the code transmitting relay 3CTP is governed by coding contacts operating at the 75 code rate subject to the back contact 26 of the track relay 3TR.

In Fig. 1C, it will be seen that the energizing circuit for the code transmitting relay 6CTP under normal conditions is closed from (+), through a circuit including back contact 30 of track relay 6TR, coding contacts 120CT, front contact 31 of relay 5H, code transmitting relay 6CTP, back contact 32 of directional stick relay 6S, to (-). With this code transmitting relay 75

6CTP being governed by coding contacts operating at the 120 code rate subject to the back contact 30 of the track relay 6TR, it will be seen that the beat code in the track section 3-6T is a combination of the 75 and 120 code rates as described above.

The energizing circuit for the transmitting relay 5CTP may be traced from (+), through a circuit including back contact 33 of track relay 5TR, coding contacts 120CT, front contact 34 of relay 6H, windings of code transmitting relay 5CTP, back contact 35 of directional stick relay 5S, to (-).

At the other end of the track section 5-8T, the transmitting relay 8CTP (see Fig. 1D) has an energizing circuit closed from (+), through a circuit including back contact 36 of track relay 8TR, coding contacts 75CT, front contact 37 of relay 8D, code transmitting relay 8CTP, back contact 38 of directional stick relay 8S, to (-).

The code transmitting relays for the siding section 7-2T are similarly operating under beat code conditions. With reference to Fig. 1D, it will be seen that the energizing circuit for the code transmitting relay 7CTP may be traced from (+) through a circuit including back contact 39 of track relay 7TR, coding contacts 75CT, front contact 40 of relay 8H, front contact 41 of relay 7H, code transmitting relay 7CTP, to (-). Referring to Fig. 1A, the energizing circuit for the transmitting relay 2CTP under normal conditions may be traced from (+), through a circuit including back contact 42 of track relay 2TR, coding contacts 120CT, back contact 43 of the series relay repeater 1SRP, front contact 44 of relay 2H, code transmitting relay 2CTP, to (-).

Although the siding ends A and B of Figs. 1A and 1D respectively may be for entirely different passing sidings, they are typical of the opposite ends of the same passing siding and Fig. 1A may be placed to the right of Fig. 1D as indicated in Fig. 2A. Thus, the code transmitting relay 7CTP is being governed by coding contacts operating at the 75 code rate while the code transmitting relay 2CTP at the other end of the siding section is being governed by coding contacts operating at the 120 code rate. Thus, the beat code in the siding section 7-2T as formed by placing Fig. 1A to the right of Fig. 1D, is in accordance with the 75 and 120 code rates applied under beat code conditions as described specifically in connection with the track section 1-4T.

The track relays are energized under beat code conditions normally existing at recurrent intervals frequently enough to energize and maintain energized a home relay H, which is made sufficiently slow-releasing in the usual way to hold over the time intervals between successive operations of the associated track relay. Accordingly, the home relays 1H, 2H, 3H, etc. for all of the signals are normally energized.

The intermittent energization of a track relay under beat code conditions, however, is not at a uniform code rate, such as 120 or 180 times per minute, suitable for providing a control for the clear indication of a signal as distinctive from a caution indication. In other words, the coding operation of a track relay under beat code conditions is not uniform at the distinctive clear code rate required for the decoding means to have sufficient output for the effective energization of a distant relay D; and consequently under beat code conditions, each distant relay is not effectively energized by its regular energizing circuit.

However, referring to Fig. 1A, it can be seen that the distant relay 1D for the head-block signal 1 is provided with an additional winding and a stick circuit including its own front contact 45 and a front contact 46 of the associated home relay 1H, so that once this distant relay 1D has been energized in response to the reception of a clear code without interference, it is maintained energized by its stick circuit under beat code conditions by its home relay 1H so long as code pulses are being received to hold up this home relay 1H. The same is true for the distant relay 8D for the head-block signal 8, and also in the form of the invention as shown in Fig. 1B for the distant relay 3D for the intermediate signal 3. The distant relays D for the entering signals 1 and 2 and the other intermediate signals 4, 5, and 6 are not provided with such a stick circuit, and hence are deenergized under the normal beat code conditions.

Thus, under normal conditions, as shown in Figs. 1A to 1D, inclusive, and as illustrated in the diagram Fig. 2A, the head-block signals 1 and 8 indicate clear to permit a train to enter the stretch at either end. The intermediate signal 3 is also controlled to indicate clear, but being approach lighted does not display any indication; and the other intermediate signals are controlled to indicate caution when lighted while the entering signals 2 and 7 are controlled to indicate stop when lighted.

It might be well to note at this time, that in the diagrams of Figs. 2A to 2V, the signal symbols have semaphore arms in positions indicating the controlled conditions of the corresponding signals although they are not actually illuminated except in the case of the head-block signals 1 and 8 which are always illuminated. In this way, the diagrams clearly indicate the control of the signals under various conditions of traffic disregarding their approach lighting control.

This approach lighting control for the intermediate signals is effected by picking up of the proper series relay in each case, but in the case of the entering signals 2 and 7 the approach lighting is accomplished by the deenergization of the home relay H for the opposing head-block signal. This is pointed out so that the use of the series relays with these signals 2 and 7 to effect a positive control and check on the signals in connection with the siding overlap (as will be later explained) will not be confused with the approach lighting control provided for these signals.

East-bound train movements.—Considering the operation for a typical east-bound train movement into and through the single track stretch shown in Figs. 1A to 1D, it is convenient to disregard for the present the effect of a train passing through the siding section 1—2T and to assume that the train making the east-bound movement comes off the passing siding at the siding end A in Fig. 1A and immediately passes into the track section 1—4T. With the train standing on the passing siding, the trainman can see that the head-block signal 1 is displaying a clear proceed indication so that such train may proceed subject to its train orders. The trainman throws the track switch AW to its reverse position, and as soon as this is done, suitable switch box contacts (not shown) serve to shunt the track section 1—2T which is supplemented by the train shunt as the train passes over the track switch via the track section 1—2T into the track section 1—4T; and the track section 1—2T re-

mains shunted until a trainman restores the track switch AW to its normal position.

When the track section 1—2T becomes shunted, the coding operation of the track relay 2TR stops and the home relay 2H and the distant relay 2D drop away. The closure of back contact 44 of the relay 2H connects the code transmitting relay 2CTP to coding contacts 18OCT through back contact 44 of relay 2H, back contact 47 of relay 1SRP, and front contact 48 of relay 1H, but this circuit is closed only until the relay 1H drops away upon the passage of a train into the track section 1—4T in a manner presently to be described. Furthermore, while the track section 1—2T is shunted or occupied by a train any coding operation of the code transmitting relay 2CTP is ineffective to be received at the other end of the siding section.

When this train enters the end track section 1—4T, coding operation of the track relay 1TR stops due to the shunting action of the train, and the home relay 1H and in turn the distant relay 1D are released, connecting transmitter relay 1CTP through the back contacts 49 and 21 of these relays 1H and 1D and back contact 50 of the relay 2H to coding contacts 75CT. Also, the series relay 1SR is energized and in turn its slow-release repeater relay 1SRP through front contact 55 of relay 1SR; and when home relay 1H releases, a pick-up circuit for the directional stick relay 1S is temporarily energized, prior to the release of the slow-release home repeater relay 1HP, from (+), through back contact 51 of relay 1H, front contact 52 of relay 1HP, front contact 53 of series repeater relay 1SRP, directional stick relay 1S, to (-). When the relay 1S becomes picked up, it is maintained energized by a stick circuit through its own front contact 54 and back contact 51 of relay 1H, until the track section 1—4T has been vacated and code pulses are received to energize relay 1H.

The energization of the directional stick relay 1S opens at its back contact 22, the energizing circuit for the transmitter relay 1CTP, so that it no longer operates, even though the relays 1H and 1D are deenergized and the energizing circuit for this transmitter relay is otherwise closed. Consequently, code pulses are not applied to the track rails of this track section 1—4T behind the train in question. This causes the series relay 1SR to cease its operation resulting in the release of its repeater relay 1SRP. Thus, although the relay 2H is picked up when the siding section 1—2T becomes unshunted and the east-bound train is wholly in track section 1—4T, the signal 2 displays a stop indication by reason of an energizing circuit for its red lamp R closed from (+), through a circuit including back contact 46 of relay 1H, back contact 56 of relay 1SRP, lamp R of signal 2, to (-). Also, the release of relay 1H closes back contact 51 to cause the red lamp R of the signal 1 to be illuminated in the rear of the east-bound train.

The entrance of the east-bound train in question into the end track section 1—4T also stops coding operation of the track relay 4TR (Fig. 1B) at the opposite end of this track section, and causes release of the associated home relay 4H to open at its front contact 28 the energizing circuit for the transmitter relay 3CTP and stop transmission of code pulses east in the adjacent track section 3—6T.

Similarly, coding operation of the track relay 6TR (Fig. 1C) stops and home relay 6H releases, opening at its front contact 34 the energizing

circuit for transmitter relay 5CTP and stopping transmission of code pulses east in the end track section 5—8T, thereby in turn stopping coding operation of the track relay 8TR and deenergizing the home relay 8H and in turn distant relay 8D to put the opposing head-block signal 8 to stop.

The deenergization of the home relay 8H (Fig. 1D) opens at its front contact 40 the energizing circuit for the transmitter relay 1CTP, thereby stopping transmission of code pulses east in the siding section 7—2T.

Referring to Fig. 1A placed at the right of Fig. 1D, as indicated in Fig. 2B, to illustrate the control through a passing siding, the effect of this tumble-down control and cessation of code pulses east in the siding track section 7—2T, is to stop coding operation of the track relay 2TR and release the home relay 2H, thereby providing for the control of the transmitter relay 2CTP at a code rate determined by traffic conditions in the adjoining single track stretch. Assuming no other train in the adjacent single track stretch, the transmitter relay 2CTP is energized at a special 180 code rate by a circuit (Fig. 1A) which may be traced from (+), back contact 42 of track relay 2TR, coding contacts 180CT, front contact 48 of relay 1H, back contact 47 of relay 1SRP, back contact 44 of relay 2H, and relay 2CTP, to (—). This change in the code rate of the pulses transmitted over the siding track section 7—2T from 120 to 180 without any interference by opposing beat code pulses energizes the distant relay 1D (Fig. 1D) and connects transmitter relay 8CTP to coding contacts 120CT through back contacts 58 and 37 of the home relay 8H and distant relay 8D, and front contact 59 of relay 1D, thereby causing the control of the intermediate signal 5 to change from caution to clear.

In this way, the entrance of an east-bound train into the stretch stops transmission of code pulses in the opposite direction in each of the track sections, puts to stop the opposing signals 4, 6 and 8, and allows the intermediate signals 3 and 5 governing east-bound train movement to be governed by code rates without interference in accordance with traffic conditions.

These conditions are diagrammatically represented in Fig. 2B.

Referring to Fig. 1B, the series relay 4SR is energized sufficiently to pick up its contacts during each code pulse transmitted by relay 4CTP upon the entrance of the east-bound train under consideration into the end track section 1—4T, or after this train has progressed part of the way through this track section, dependent upon the operating characteristics of this series relay; and this causes energization of the series repeater relay 4SRP through front contact 60 so that it picks up and remains picked up, so long as 4SR continues to operate, to approach light the signal 3, and to also establish conditions for the energization of the directional stick relay 3S when the train passes the intermediate signal 3. More specifically, signal 3 is illuminated by reason of a circuit closed from (+), through a circuit including front contact 61 of relay 4SRP, front contact 62 of relay 3H, front contact 63 of relay 3D, green lamp G of signal 3, to (—). This same approach lighting control by a series relay is characteristic of the other intermediate signals, and need not be again described with respect to these other signals.

When the east-bound train under consideration passes the first intermediate signal 3 into the track section 3—6T, coding operation of the track relay 3TR stops, and the relay 3H is deenergized to put the signal 3 to stop and also release the distant relay 3D by opening its stick circuit at the front contact 64 of relay 3H. Also, the release of the home relay 3H prior to the release of its slow-release repeater relay 3HP closes a pick-up circuit for the directional stick relay 3S from (+) through a circuit including back contact 65 of relay 3H, front contact 66 of relay 3HP, back contact 67 of relay 4S, front contact 68 of relay 4SRP, relay 3S, to (—). The control for this directional stick relay is similar to that described for the directional stick relay 1S of Fig. 1A except that this directional stick relay 3S is interlocked with the directional stick relay 4S associated with the opposing intermediate signal 4 and thus includes the back contact 67 of relay 4S. Also, it will be noted that the series relay repeater 4SRP having front contact 68 included in the pick-up circuit for relay 3S, is associated with the track section in the rear of the signal 3 instead of the section in advance. This differs slightly from the control for the directional stick relay 1S for reasons which will be later pointed out. The directional stick relay 3S is stuck up so long as the home relay 3H is maintained deenergized by the presence of the train in the track section 3—6T in advance of the signal 3 by reason of a stick circuit including back contact 65 of relay 3H and its own front contact 69.

Under these conditions, with the home relay 3H deenergized and the directional stick relay 3S energized, the transmitter relay 4CTP for the track section 1—4T in the rear is connected to coding contacts 75CT through the back contact 24 of relay 3H and a front contact 70 of relay 3S, thereby providing code pulses at the 75 caution code rate for the track section 1—4T in the rear; and as soon as this track section becomes unoccupied, the track relay 1TR is operated by these code pulses and energizes the home relay 1H, but not the distant relay 1D, to provide a caution indication for the head-block signal 1 for following train movements. The energization of the directional stick relay 3S also prevents operation of the transmitter relay 3CTP at open back contact 29, so that there are no code pulses behind the train in question while it is moving through the track section 3—6T in advance of the signal 3.

Referring to Fig. 1A, when the home relay 1H is energized by the caution code in the rear of the east-bound train in question, it opens its back contact 49 in the energizing circuit for the transmitter relay 1CTP at the same time that it breaks its back contact 51 in the stick circuit for the directional stick relay 1S and thus permits this relay 1S to drop away and close its back contact 22 in the energizing circuit for the transmitter relay 1CTP. Consequently, the circuit for relay 1CTP is maintained open during this change in condition and there are no code pulses transmitted east in the end track section 1—4T to tend to clear the intermediate signal 4 or establish normal beat code conditions in this track section. These conditions just described are diagrammatically indicated in Fig. 2C.

As the east-bound train under consideration advances and passes the next intermediate signal 5, it puts this signal to stop, energizes the associated directional stick relay 5S, and provides

a 75 caution code in the rear track section 3-6T to cause signal 3 to indicate caution for a following train movement, in the same manner just described. The energization of the home relay 3H (Fig. 1B) by this caution code drops the directional stick relay 3S; but the energizing circuit for the transmitter relay 3CTP is opened at the back contact 71 of the relay 3H before the relay 3S drops to close back contact 29, so that there are no code pulses transmitted east in the track section 3-6T to control signal 6.

The energization of the home relay 3H and the closure of its front contact 24 establishes the normal circuit for operating the transmitter relay 4CTP at the 120 code rate; and the change in the code rate in the track section 1-4T from 75 to 120 causes energization of the distant relay 1D as well as the home relay 1H. This energization of the distant relay 1D establishes the normal energizing circuit for the transmitter relay 1CTP to restore normal beat code conditions in the end track section 1-4T, the distant relay 1D being maintained energized by its stick circuit under these beat code conditions to provide a clear indication for the head-block signal 1. The home relay 4H (Fig. 1B) is also energized under these beat code conditions to provide a caution control for the intermediate signal 4. These conditions are indicated diagrammatically in Fig. 2D.

As previously mentioned, the entrance of a train into any particular track section, or at least when the train has passed into the track section a sufficient distance, the series track relay SR at the leaving end of the section receives sufficient energization during the code pulses applied to such leaving end to be picked up for each pulse and thereby intermittently energize its repeater relay SRP, which is sufficiently slow-release in its characteristics to remain picked up between successive energizations. Each of these series relay repeaters SRP associated with an intermediate signal is then used for approach lighting that signal, but when a train enters the single track stretch and effects the tumble-down operation, the entering signal is approach lighted by the dropping away of the home relay H for the associated head-block signal. For example, the east-bound train under consideration causes the deenergized condition of the relay 8H and thereby closes an energizing circuit for the red lamp of signal 7 from (+), through a circuit including back contact 72 of relay 8H, back contact 73 of relay 8SRP, red lamp R of signal 7, to (-).

Thus, when the train initially enters the track section 5-8T the signal 7 is already illuminated, but as soon as the train has entered the section a sufficient distance the picking up of the series relay 8SR for each of the code impulses results in the picking up of its repeater relay 8SRP, which shifts the circuit for the signal 7 so that such signal 7 is illuminated in accordance with the code received by the relays 7H and 7D. More specifically, the east-bound train in the track section 5-8T under the conditions assumed, as indicated in the diagram of Fig. 2D, causes the signal 7 to display a green proceed indication by reason of an energizing circuit closed from (+), through a circuit including back contact 72 of relay 8H, front contact 73 of relay 8SRP, front contact 77 of relay 7H, front contact 78 of relay 7D, green lamp G of signal 7, to (-). In this way, the signal 7 is cleared so that the east-bound train may proceed.

Assume now that the east-bound train under consideration passes the entering signal 7 into the siding track section 7-2T. This causes de-energization of the home relay 7H and the distant relay 1D (see Fig. 1D) thereby putting the signal 7 to stop, and also connecting the transmitter relay 8CTP to coding contacts 75CT through the back contacts 58 and 37 of the relays 8H and 8D and back contacts 59 and 79 of relays 1D and 1DX, so that code pulses at the 75 caution code rate are transmitted toward the intermediate signal 5. This caution code first causes energization of the home relay 5H (Fig. 1C) which releases the directional stick relay 5S; but since the home relay 6H is deenergized at this time, there being no code pulses east toward signal 6 (see Fig. 2D), there is no operation of the transmitter relay 5CTP when relay 5S drops. The energization of the relay 5H, however, changes the code rate in the track section 3-6T in the rear of signal 5 from 75 to 120, thereby energizing the distant relay 3D (Fig. 1B) and closing the normal energizing circuit for the transmitter relay 3CTP to establish the normal beat code conditions in the track section 3-6T. This causes energization of the home relay 6H (Fig. 1C) which closes its front contact 34 to initiate operation of the code transmitter 5CTP by coding contacts 120CT. Code pulses at the 120 code rate are thus applied to the west end of the track section 5-8T to combine in a beat code fashion with the code pulses at the 75 code rate being transmitted at that time from the other end of this track section; and the result is the energization of the home relay 8H (Fig. 1D) which opens at its back contact 58 the circuit for the transmitter relay 8CTP, thereby stopping transmission of the code pulses west in this track section. Under these conditions, the track relay 8TR may be operated uniformly without interference at the 120 clear code rate and energize the distant relay 8D; and as soon as this relay 8D is energized, it closes its front contact 37 to establish the normal circuit connecting the transmitter relay 8CTP to coding contact 75CT and restore normal beat code conditions in this end track section.

It can be seen that the removal of the code pulses at the 75 code rate west in this end track section 5-8T upon energization of the home relay 8H is only temporary for the relatively short time required for the energization of distant relay 8D as soon as its associated track relay 8TR starts coding operation at a uniform clear code rate; and the operating characteristics of the relays as ordinarily used is such that the energizing time for the distant relay 8D is less than the release time for the home relay 5H, so that no tumble-down action occurs. Obviously, if necessary an additional time delay in the tumble-down control may be introduced by using a front contact on the repeater relay 5HP to perform the functions of the contact 31 shown on the relay 5H.

These conditions just described are diagrammatically indicated in Fig. 2E, where the successive conditions for the track section 5-8T should be read from left to right.

With this explanation, it can be readily seen how this system operates for east-bound train movements into and through the stretch of single track between passing sidings to put to stop the opposing signals and allow the signals in the rear to indicate caution and clear for following train movements, and in general affords the same

safety and facility characteristic of the usual A. P. B. system.

During the east-bound train movement through the single track stretch just described, there is also the control of the opposing entering signal 2 and intermediate signal 4 in the rear thereof for the adjacent single track stretch to provide the double distant and siding overlap control; but this operation is more conveniently considered later.

West-bound train movements.—The tumble-down operation and directional control to put all opposing signals to stop and allow signals in the rear of a train to clear for following trains is substantially the same for west-bound train movements as for east-bound train movements, but there are slight differences in the way in which normal beat code conditions are restored which makes it expedient to outline briefly the operation for a west-bound train movement.

When a west-bound train enters the single track stretch as indicated in Fig. 2F, beat code pulses west in each track section of the stretch are stopped by the tumble-down action to put the opposing signals 1, 3, and 5 to stop. When the home relay 3H and also the distant relay 3D for signal 3 are thus deenergized, the transmitter relay 3CTP (Fig. 1B) for providing a code to govern the indication of the intermediate signal 6, is connected through the back contacts 21 and 27 of the relays 3H and 3D and a front contact 28 of the home relay 4H through coding contacts 120CT to provide code pulses at the 120 clear code rate east in the track section 3—6T, and thereby energize the distant relay 6D as well as the home relay 6H, and change the indication of signal 6 from caution to clear.

Similarly, the deenergization of the home relay 1H and the distant relay 1D (Fig. 1A) establishes a circuit through their back contacts 49 and 51 for the transmitter relay 1CTP to cause its operation by coding contacts dependent upon the condition of the relay 2H. Assuming no other train present and relay 2H energized, the transmitter relay 1CTP is connected to coding contacts 120CT, and transmits a clear code to cause the intermediate signal 4 to indicate clear. In other words, the distant control for signal 2 is for a clear control of such signal 2 and thereby permits the signal 4 to indicate clear, although signal 2 is actually displaying a stop indication and will not display a clear indication until the train enters the track section 1—4T as will be presently explained.

In the case of a west-bound train movement, for reasons later considered in discussing the double distant and siding overlap control, coding through the siding track section 7—2T at the other end of the stretch is not effected, as in the case of an east-bound train movement, at least until the west-bound train enters the end track section, as indicated in Fig. 2H.

When the west-bound train under consideration passes the first intermediate signal 6, as shown in Fig. 2G, there is a caution 75 code east in the end track section 5—8T in the rear of the signal 6 for causing the head-block signal 8 to indicate caution, and also there is no coding west in this end track section behind the train, due to the energization of relay 8H before release of relay 8S, in the same manner above discussed for an east-bound train movement.

When the west-bound train passes the second intermediate signal 4, as shown in Fig. 2H, code pulses at the 75 code rate are transmitted east behind this train in track section 3—6T. The

energization of the home relay 6H (Fig. 1C) and closing of its front contact 34 closes the normal circuit for the transmitter relay 5CTP to provide a code at the 120 clear code rate to cause the head-block signal 8 to indicate clear and establish beat code conditions in the corresponding end track section 5—8T in the same manner previously explained. The release of the directional stick relay 6S and the energization of the home relay 5H under these normal beat code conditions initiates operation of the transmitter relay 6CTP at the 120 code rate, thus restoring normal beat code conditions in the track section 3—6T. This causes energization of the relay 3H, but not the distant relay 3D, since the transmitter relay 3CTP under these conditions is maintained in operation at the 75 code rate by its circuit through the back contact 28 of relay 4H and a front contact 81 of the directional stick 4S, and the operation of the track relay 3TR by the beat code pulses is not at the uniform high code rate sufficient to pick up the distant relay 3D.

Thus, in the case of a west-bound train movement, the second intermediate signal 3 behind this train receives a caution control due to the restoration of beat code conditions, as indicated in Fig. 2H, instead of remaining at stop as in the case of the corresponding signal 6 for east-bound train movement as shown in Fig. 2D. However, with the signal 3 approach lighted in the manner shown by the series relay 4SR, this signal is not lighted under these conditions, since there is no operation of the transmitter relay 4CTP due to the energization of the directional stick relay 4S by the train in question; and the signal 3 does not display any indication permitting a train to make a back-up movement, a condition which is desirable for reasons later considered in connection with the discussion of back-up train movements. If the intermediate signal 3 is normally lighted, or approach lighted in some different manner so as to be lighted with a west-bound train in the rear of it as shown in Fig. 2H, then it may be desirable to make provision in accordance with recognized practice to prevent clearing of signal 3 while the directional stick relay 4S for its associated opposing intermediate signal 4 is energized.

When the west-bound train under consideration passes out of the end track section 1—4T of the single track stretch, code pulses at the 75 code rate are first transmitted east in this end track section and energize the home relay 4H to open at its back contact 28 the circuit at that time energizing the transmitter relay 3CTP by coding contacts 15CT, this circuit being through the back contact 28 of the relay 4H and the front contact 81 of relay 4S. For reasons previously explained, at the time the home relay 4H is thus energized, the home relay 3H is energized but not the distant relay 3D; and consequently the operation of the transmitter relay 3CTP is temporarily discontinued until the coding operation of the track relay 3TR at the uniform 120 clear code rate without interference by opposing code pulses causes energization of distant relay 3D to close its front contact 21 and establish the normal circuit for transmitter relay 3CTP, thereby restoring normal beat code conditions in the track section 3—6T.

The energization of the relay 4H also releases the directional stick relay 4S and permits transmitter relay 4CTP to be operated by coding contacts 120CT by its normal energizing circuit through the front contact 24 of relay 3H; and the beat code conditions thus set up in the end track section 1—4T cause the picking up of

the relay 1H opening back contact 49 to temporarily discontinue the coding operation of the transmitter relay 1CTP. This allows an unopposed 120 clear code to be received at the head-block signal 1 to effect the picking up of the relay 1D as well as the relay 1H. As soon as front contact 21 of relay 1D is closed, the relay 1CTP is connected to coding contacts 75CT, so that normal beat code conditions are restored in the end track section 1-4T. These various conditions have been indicated in the diagram of Fig. 2J, and the symbols indicating these conditions may be read for each track section from left to right, it being seen that there is a momentary cessation of code pulses east in both the end section and the intermediate section to permit an unopposed code to pick up the respective D relays. However, from the above description and noting the diagram of Fig. 2J, it will be seen that these momentary periods of cessation of code pulses east in the two track sections do not occur at the same time in the sequence of restoring conditions. It will be also noted that the restoration conditions in this end track section 1-4T are the same as above described in connection with the east-bound train movement out of the stretch and pointed out in connection with Fig. 2E.

When a train follows another train in the single track stretch under either clear or caution signal indications, the second train produces the same tumble-down control to put opposing signals to stop and provides the same directional control to permit signals in the rear to clear for other following train movements, in the same manner as the first train to enter the stretch; and the operation of the system for the case of two trains following one another in the same direction can be readily apparent from the foregoing discussion without any further discussion.

Double-distant and siding overlap control.—With two opposing trains approaching a passing siding, a special control of the entering signals and the intermediate signals in the rear thereof is required to afford the necessary signal protection. This special control, characteristic of the well known A. P. B. system, is commonly known as a conditional double distant and siding overlap control and is provided in the system of the present invention as indicated in the diagrams of Figs. 2K to 2N. It will be seen from these diagrams that the system provides various coding conditions for the different possible positions of the opposing trains, but this special control provided to give protection for opposing trains does not in any way interfere with the usual spacing and control for following train movements which has been indicated in Figs. 2P to 2S, and which will be considered later.

When two opposing trains approach a passing siding with the switches at the ends of these sidings in the normal position as indicated in the diagram of Fig. 2K, it can be seen that these trains are in effect travelling toward each other on the same stretch of track and require adequate opposing signal protection. This is accomplished by providing what is known as a siding overlap for one track section at each end of the siding. For example, when an east-bound train approaching a passing siding enters the end track section 5-8T in the rear of the entering signal 7, as indicated in Fig. 2D, the opposing entering signal 2 should be at stop for any west-bound train in the adjacent single track stretch

approaching this siding; and similarly with a west-bound train in the end track section 1-4T in the rear of the entering signal 2 and in the position indicated in Fig. 2H, the opposing entering signal 7 should be at stop for an east-bound train in the other single track stretch approaching that signal. In short, there should be an overlap control in each direction for the entering signals 2 and 7 to prevent opposing trains entering the same portion of track under favorable signal indications.

Since an entering signal, such as the signal 2, may thus be put to stop by this overlap control upon the entrance of an east-bound train into the other end track section at the time a west-bound train is approaching this signal 2 (see Figs. 2M and 2N) and is required to stop, it can be appreciated that it is important to provide a special control for the intermediate signal, such as the signal 4, in the rear of this entering signal 2, so as to give an advance warning of this condition. Thus, when an east-bound train enters the single track stretch and puts to stop the opposing head-block signal 8 as in Fig. 2B, not only should the entering signal such as the signal 2 in the rear of this head-block signal 8 indicate caution, but also the intermediate signal 4 in the rear of this entering signal 2 should indicate caution, so as to provide a so-called double distant caution indication. The same is true for the entering signal 7 and its associated intermediate signal 5.

This siding overlap and double distant control required for opposing trains is not needed for following trains; and it is desirable to make these controls conditional on the direction of train movement. For example, if the end track section 5-8T is occupied by a west-bound train, as shown in Fig. 2F, there is no need for the entering signal 2 in the rear to indicate stop, nor the intermediate signal 4 in the rear of this entering signal 2 to indicate caution, it being sufficient to protect the train in question against following trains to have a caution indication for the entering signal 2 and a clear indication for the intermediate signal 4.

With this general and brief explanation of the nature and requisites of conditional siding overlap and double distant control of signals in an automatic block signaling system for single track railroads of the A. P. B. type, consideration may now be given to the way in which these desired controls are obtained in the coded track circuit system of this invention without line wires. In this connection, reference will be made to Figs. 1C, 1D, 1A, and 1B arranged end to end in the order named to represent the organization of the system for a complete passing siding and the end track sections of adjacent single track stretches.

Assume first that two opposing trains E and W have entered the adjacent single track stretches as indicated in Fig. 2K. When the east-bound train E entered its single track stretch, the tumble-down control caused cessation of code pulses east in the siding track section 7-2T, in the manner previously explained, thus releasing the home relay 2H and rendering the code rate transmitted west in this siding track section dependent upon the traffic conditions in the other single track stretch. With the opposing train W in this other single track stretch, the home relay 1H is deenergized, so that the transmitter relay 2CTP (Fig. 1A) is connected to coding contacts 75CT through a back contact 44 of relay 2H, back contact 41 of relay 1SRP, back contact 48 of

relay 1H and back contact 80 of relay 1S. The transmission of code pulses at the 75 code rate west in the siding track section 1-2T energizes the home relay 1H, but not the relay 1D or 1DX, so that signal 1 is controlled to caution, and the code pulses transmitted toward the intermediate signal 5 by the transmitter relay 8CTP are at the caution 75 code rate to cause this signal 5 to give the desired double distant caution indication.

Also, with the east-bound train E causing de-energization of the home relay 2H, and with the west-bound train causing deenergization of relays 1H and 1D, the relay 1CTP (Fig. 1A) is connected through the back contacts 49 and 21 of relays 1H and 1D, and the back contact 50 of the home relay 2H to coding contacts 75CT, thereby transmitting code pulses toward the intermediate signal 4 at the 75 caution code rate, instead of at the 120 clear code rate as shown in Fig. 2F, and causing this signal 4 to display the desired double distant caution indication.

Assume now that the east-bound train E passes the signal 5 into the end track section 5-8T while the west-bound train W is still in the rear of the intermediate signal 4, as shown in Fig. 2L. The series relay 8SR and its repeater relay 8SRP are energized by the train E; but since the home relay 1H (Fig. 1D) is still energized under these conditions, this energization of the series repeater relay 8SRP does not cause any change in coding conditions. However, it does cause the signal 1 to display a caution indication so that the train E can proceed into the siding section 1-2T, while the train W is approaching signal 4 at caution.

Assume now that the west-bound train W passes the intermediate signal 4 and enters the end track section 1-4T while the east-bound train E is still in the rear of the intermediate signal 5, as shown in Fig. 2M. The entrance of the train W into the end track section 1-4T, or at least when this train has advanced within sighting distance of the signal 2, causes energization of the series relay 1SR and its repeater relay 1SRP to open at its back contact 47 the circuit at this time connecting the transmitter relay 2CTP to the coding contacts 75CT through back contacts 48 and 80. Consequently, transmission of code pulses west in the siding section 1-2T ceases, and relay 1H is deenergized, putting the signal 1 to stop for the desired siding overlap control, and also establishing an energizing circuit for the transmitter relay 1CTP to coding contacts 75CT through the back contact 41 of relay 1H, back contact 82 of relay 8SRP, and back contact 83 of relay 8H. In this way, the direction of coding in the siding track section is automatically reversed by the approach of the west-bound train W to change the indication of signal 2 from stop to caution.

More specifically, the transmission of the 75 caution code east in the track section 1-2T, causes the picking up of the home relay 2H so that with the series repeater relay 1SRP picked up, an energizing circuit is closed for the yellow lamp Y of signal 2 from (+) through a circuit including back contact 46 of relay 1H, front contact 56 of relay 1SRP, front contact 84 of relay 2H, back contact 85 of relay 2D, lamp Y of signal 2, to (-). Thus, the train W can proceed into the siding section 1-2T on a caution signal while the train E is approaching the signal 5 at caution, as indicated in Fig. 2M.

If the west-bound train W should enter the

end track section 1-4T and energize the series repeater relay 1SRP, at the time the east-bound train E occupies the end track section 5-8T as shown in Fig. 2N, the transmission of code pulses west in the siding track section as shown in Fig. 2L is cut off by the energization of this relay 1SRP and the opening of its back contact 47, putting the entering signal 1 to stop. Also, with the series repeater relay 8SRP energized by the train E in the end track section 5-8T at this time, the opening of its back contact 82 prevents any operation of the transmitter relay 1CTP when the relay 1H is deenergized. On the other hand, if the west-bound train W should be the first to enter the end track section 1-4T and cause a reversal in the direction of coding in the siding track section, as shown in Fig. 2M, then the subsequent entrance of the east-bound train E into the end track section 5-8T and the energization of the series repeater relay 8SRP opens its back contact 82 to cut off the transmission of the code pulses east in the siding track section to put the entering signal 2 to stop. In short, with two trains in the two end track sections approaching the passing siding as indicated in Fig. 2N, both of the entering signals 2 and 1 indicate stop for these approaching trains, no matter which train happened to enter its end track section first, thereby providing the desired siding overlap control for both directions.

In connection with this siding overlap control, it will be noted that the presence of a train in an end track section is detected by the energization of the associated series relay 1SR or 8SR; and it is important that failure of either of these series relays to be energized by the shunting action of a train should not create an unsafe condition. If these series relays are used to approach light the corresponding entering signals, the failure of a series relay to become properly energized leaves its entering signal unlighted; and to that extent, the performance of the series relay is checked. Although an unlighted dark signal should be obeyed as a stop signal, it is considered that an engineer is more likely to overlook or miss a dark signal than one that is lighted. Accordingly, it is proposed in accordance with this invention to light each of the entering signals 2 and 1 by the release of the home relays 1H and 8H for the associated head-block signals 1 and 2 upon the entrance of a train into the single track stretch, and prevent an entering signal from displaying any indication better than red or stop until the corresponding series relay has been energized. Referring to the signal 2 in Fig. 1A as typical, when a west-bound train enters the stretch (as in Fig. 2F) and drops the relay 1H, the red lamp R is lighted by a circuit through the back contact 46 of the relay 1H and back contact 56 of relay 1SRP; but if the series relay repeater 1SRP is properly energized when this train enters the end track section 1-4T (as in Fig. 2H) the green lamp G is lighted if the distant relay 2D is energized by a circuit through the back contact 46 of relay 1H, front contact 56 of relay 1SRP, front contact 84 of relay 2H and front contact 85 of relay 2D. If the home relay 2H is energized and the distant relay 2D is deenergized, the yellow lamp Y is lighted by a circuit similar to the one just traced through the back contact 85 of relay 2D; and if the home relay 2H is deenergized, the red lamp R is lighted.

In this way, the response of the series relay providing siding overlap control is checked be-

cause the associated entering signal will indicate stop unless the corresponding series relay operates properly. Any train approaching this entering signal will be warned by the double distant caution indication if there should be an opposing train approaching the siding from the opposite direction and will stop at this entering signal held at stop by the failing series relay, so as not to get in the way of such opposing train that may, in the absence of the siding overlap control that should have been effected by such failing series relay, accept the opposing entering signal at caution and advance as far as the corresponding head-block signal.

Considering now the operation of the system with respect to the control of entering signals and associated intermediate signals in the rear thereof for following train movements, assume an east-bound train E is approaching the passing siding and is following another east-bound train EE ahead which has just left the passing siding, as indicated in Fig. 2P. When this train EE ahead passed the head-block signal 1, it picked up the directional stick relay 1S (Fig. 1A) which opens its back contact 22 and prevents operation of the code transmitter relay 1CTP, so that the series relay 1SR is not energized by this train. The stick relay 1S also closes its front contact 80 to connect the coding contacts 120CT through back contact 44 of relay 2H now de-energized by the approaching train E, back contact 47 of series relay repeater 1SRP, back contact 48 of relay 1H and front contact 80 of relay 1S. Consequently, code pulses at the 120 code rate are transmitted toward the entering signal 7 which energize the special distant relay 7DX but not the distant relay 7D. With the distant relay 7D deenergized, the entering signal 7 is controlled to indicate caution, but it actually displays stop because relay 8SRP is still down. The energization of the special distant relay 7DX establishes a circuit through its front contact 79 to operate the transmitter relay 8CTP at the clear 120 code rate from the coding contacts 120CT, thereby providing a clear indication for the intermediate signal 5. Should the train E enter the section 5-8T with the train EE still in section 1-4T, the series relay 8SRP would be picked up and signal 7 would be caused to display a caution indication.

If the train EE ahead, in the case assumed, has passed the intermediate signal 3 by the time the east-bound train E is approaching the entering signal 7, as shown in Fig. 2Q, the energization of the home relay 1H by the caution code establishes the circuit for the transmitter relay 2CTP through back contact 44 of relay 2H, back contact 47 of relay 1SRP, and front contact 48 of relay 1H to coding contacts 180CT, thereby changing the code rate in the siding track section from 120 to 180, and causing the entering signal 7 to indicate clear for the east-bound train E.

Considering now the case where a west-bound train W is approaching the passing siding and following another west-bound train WW ahead which has just left the siding, as shown in Fig. 2R, the energization of the directional stick relay 8S by the train ahead provides a shunt through its front contact 86 (see Fig. 1D) around the front contact 40 of the home relay 8H, so that normal beat code conditions are maintained in the siding track section 7-2T, and the home relay 2H is energized to provide a clear 120

code toward the signal 4 to cause that signal to indicate clear for the approaching train W.

The energization of the directional stick relay 8S by a forward train WW in the case assumed 5 also prevents operation of the transmitter relay 8CTP and energization of the relay 8SRP, so that when the west-bound train W enters the end track section 1-4T and approaches the entering signal 2, as shown in Fig. 2S, the energization of the series relay repeater 1SRP by this train stops coding west in the siding track section, and a caution code is received to give the signal 2 a caution indication for the approaching train W.

15 If the train WW ahead has advanced beyond the intermediate signal 6, at the time the west-bound train W under consideration entered the end track section 1-4T and picked up the relay 1SRP to provide coding east in the siding track 20 section without interference, then the home relay 8H being energized, the code transmitted toward the signal 2 is at the 180 clear code rate to give that signal 2 a clear indication.

Thus, when a train approaching a passing siding is following another train ahead travelling in the same direction, the signals display the regular clear, caution and stop indications for the following train, the same as on a double track railroad.

30 In connection with the coding through the siding track section 7-2T for conditional double distant control, it will be noted that no directional stick relay has been disclosed in connection with entering signals 2 and 7, although one 35 might be used if desired, and hence code pulses are applied to both ends of this siding track section when it is first vacated by a train. For example, referring to Figs. 1D and 1A, placed end to end, when the siding track section 7-2T 40 is occupied by a train, the home relays 1H and 2H are both deenergized, and the transmitter relay 1CTP and 2CTP will apply code pulses behind this train, as well as in front of it. Consequently, when this train leaves this track section, 45 the track relays 7TR and 2TR are subjected to the combined effect of these code pulses. Unless these code pulses are applied in the opposite ends of the siding track section 7-2T under these conditions by coding contacts closing 50 at exactly the same time intervals, there will be an energization of the track relays 2TR and 7TR sufficient to energize the home relays 2H and 1H to restore normal conditions. In the arrangement shown, code rates of 75, 120 and 55 180 have been chosen for coding west in the siding track section to provide the desired yellow-yellow, yellow-green and green-green indications for the signals 1 and 5 for conditional double distant control. For the other direction 60 code rates of 75 and 180 have been chosen as suitable for providing caution and clear indications for the entering signal 2 when it has been conditioned to give an indication more favorable than stop by the energization of the series relay 1SR by a train approaching this signal. With this choice of code rates, except for one case, the code pulses applied to the opposite ends of the siding track section 7-2T when it first becomes vacated by a train, are provided by coding contacts operated at different code rates, so that the home relays 2H and 1H are immediately restored by beat code conditions.

70 However, in the case of a west-bound train which, after passing the entering signal 2 into the siding track section, passes out of this track

section into the passing siding, instead of moving straight ahead into the other single track stretch; the transmitter relay 2CTP is connected to coding contacts 180CT through the back contact 44 of relay 2H and front contact 48 of relay 1H (assuming no following train), while the other transmitter relay 7CTP is connected to coding contacts 180CT through the back contact 41 of relay 1H and front contact 83 of relay 8H. In this case, although the transmitter relays 2CTP and 7CTP for the opposite ends of the siding track section are governed by coding contacts nominally having the same code rate of operation, it is contemplated that these coding contacts on account of unavoidable variations in manufacture or by deliberate adjustment, will vary slightly in their exact rate of operation, say 178 times a minute as compared with 180 times a minute. Hence, if it should happen that these coding contacts 180CT for the opposite ends of the siding track section are being closed synchronously at the time the siding track section becomes vacated, these coding contacts will get out of step in a short time, and cause intermittent energization of the track relays 2TR and 7TR at both ends to energize the relays 2H and 7H, thereby shifting to coding contacts having substantially different code rates, such as 75 and 120 times per minute. In this connection, it can be appreciated that two code transmitting devices operating at 180 and 178 times per minute, for example, will get out of step half of a code interval, or one complete "on" period four times a minute, or every 15 seconds. In other words, although substantially different code rates, such as 75 and 120, are preferably employed for more uniform energization of track relays under beat code conditions, a small difference in code rates is sufficient to simulate beat code conditions and cause intermittent energization of the track relay at opposite ends of the track section for restoration purposes.

Back-up moves.—It is sometimes necessary for the train, after it has entered the stretch or single track, to reverse its direction of movement for some reason and return to the passing siding at the same end of the stretch at which it entered, as for example, in the case of a work train delivering men or material to some intermediate point in the single track stretch. For reasons familiar to those skilled in the art, such a back-up move cannot be made with complete safety in an automatic A. P. B. system, and it is desirable that the intermediate signals should not clear behind a train to permit or invite a back-up move under signal indication. Accordingly, provision is usually made in an A. P. B. system to prevent clearing of an intermediate signal when the directional stick relay for the associated opposing intermediate signal is energized. In the present invention, the circuits for controlling the code transmitter relays are such that there is no code to clear an intermediate signal 4 or 6 for an east-bound train, as previously explained and indicated in Figs. 2C and 2D; and the same is true for the intermediate signal 5 for a west-bound train, as shown in Fig. 2G. As already pointed out, the other intermediate signal 3, while receiving code for a caution indication, is not approach lighted for a train to make a back-up move with the arrangement of approach lighting shown, and if this signal should be lighted, it may be prevented from clearing by energization of the directional stick relay 4S in the usual way.

While a train which has moved only beyond

the first intermediate signal such as signals 4 and 5 cannot make a back-up move without flagging all the way back to the head-block signal from which it entered the single track stretch, a train which has advanced beyond the second intermediate signal, such as signals 3 and 6, may make a back-up move under certain conditions under signal indications without flagging back all of the way. Assume, for example, that an east-bound train has advanced beyond the intermediate signal 5 as shown in Fig. 2D, and also as indicated by dotted lines in Fig. 2T, and that this train has authority by train order or otherwise to make a back-up move. If this train backs up just beyond the intermediate signal 6 at stop, with suitable flagging protection, the opposing intermediate signal 3 and head-block signal 1 are automatically put to stop by a regular tumble-down operation previously explained; and if no opposing train has entered the stretch, the intermediate signal 4 will indicate clear or caution. Under such conditions, the train may complete its back-up move without further flagging protection. In this connection, it is assumed that the train in question will merely pull past the signal 6 and then wait until a favorable indication of the intermediate signal 4 has been displayed for a time before proceeding, so that if some other train should happen to pass the head-block signal 1 at the same time the tumble-down control for this signal is initiated, such other train will have sufficient distance in which to stop after sighting the intermediate signal 3 at stop.

When a train making such a back-up move under consideration passes the intermediate signal 4, as shown in Fig. 2U, the energization of the corresponding directional stick relay 4S causes the transmitting relay 3CTP to be connected to the coding contacts 75CT so that beat code conditions are established in the track section 3—6T effecting the picking up of the home relay 6H. When the relay 6H is picked up, the code transmitting relay 5CTP is connected to coding contacts 120CT through its front contact 34. At this time, the transmitting relay 8CTP at the opposite end of the track section 5—8T is also connected to coding contacts 120CT, but as previously mentioned, although the coding contacts 120CT for the opposite ends of a track section may nominally operate at the same code rate, in practice due to inherent variations in manufacture or by deliberate adjustment these coding contacts do not have exactly the same rate and will get sufficiently out of step after a short time to intermittently operate the track relays 5TR and 8TR at the opposite ends of the track section to establish a beat code condition. Such a beat code condition needs to exist only sufficiently long to cause the home relay 8H to be picked up, which opens its back contact 58 and causes the code transmitting relay 8CTP to temporarily cease its operation. This allows a 120 driven code to be received by the track relay 8TR without interference which of course results in the picking up of the distance relay 8D which then sticks through front contact 72 on relay 8H. As soon as the relay 8D picks up, it closes front contact 37 so that the normal beat code conditions are then restored in the track section 5—8T. In other words, the cessation of operation of the code transmitting relay 8CTP is of relatively short duration just sufficient to allow the picking up of the relay 8D. These different conditions have been indicated in Fig. 2U and the

symbols indicating the conditions of restoration for the track section 5-8T should be read from left to right.

The picking up of the relay 8H closes its front contact 40 causing the code transmitting relay 7CTP to be connected to coded contact 75CT so that the normal beat code conditions are established in the siding section 7-2T in a manner readily understood from the description given above.

In brief, a back-up train movement such as indicated in Figs. 2T and 2U, causes the system to be restored to normal in the rear of signal 4 as soon as the train passes that signal in making its back-up movement, thus causing the signals 6 and 8 in the rear to clear for following train movements, the same as if a train had entered the signal track stretch by passing the head-block signal 8.

Thus, the coded track circuit signaling system of this invention affords the same facility and safety for back-up train movements in the single track stretch characteristic of the usual A. P. B. system with conventional track circuits and line wire control.

Modification of Figs. 3A and 3B.—In the arrangement illustrated in Figs. 1B and 1C for the middle track section 3-6T of the single track stretch, it can be seen from the foregoing explanation that the same 75 code rate is used for the caution control for both of the opposing intermediate signals 3 and 6, and this caution 75 code is established and maintained in one direction for normal beat code conditions by energizing a distant relay 3D by a 120 code in the other direction and maintaining this distant relay 3D energized under beat code conditions by a supplemental stick circuit.

Figs. 3A and 3B illustrate another modified arrangement in which the caution codes for the opposing intermediate signals 3 and 6 are the normal beat codes of 120 and 75, and an additional 180 code is used for the clear indications of these signals. The general operating principles of this modification of Fig. 3 with regards to the tumble-down and directional control are the same as previously described, and the distinction is in the way in which normal beat code conditions are restored after the train movements in opposite directions.

Referring to Fig. 3A, under the normal conditions shown, the transmitter relay 3CTP is connected to coding contacts 75CT by a circuit from (+), through back contact 90 of track relay 3TR, coding contacts 75CT, front contact 91 of home relay 3H, front contact 92 of home relay 4H, transmitter relay 3CTP, and back contact 93 of directional stick relay 3S, to (-). The transmitter relay 6CTP for the opposite end of this middle track section 3-6T is connected to coding contacts 120CT by a similar circuit including front contacts 94 and 95 of relay 6H and 5H and a back contact 96 of relay 6S.

When an east-bound train enters the single track stretch and deenergizes the relay 4H by tumble-down control in the same manner previously explained, coding operation of the transmitter relays 3CTP stops and home relay 6H is deenergized to put the opposing signal 6 to stop and to also stop transmission of code pulses east in the adjacent track section to put to stop the opposing head-block signal 8. Also, the deenergization of relay 6H and closing of its back contact 94 connects the transmitter relay 6CTP to coding contacts 180CT and thus provides a code 75

at the clear code rate to cause the intermediate signal 3 to indicate clear. When this east-bound train passes the intermediate signal 3, the directional stick relay 3S is energized, and when this train passes signal 5 out of the intermediate track section 3-6, the directional stick relay 5S is energized to connect the transmitter relay 6CTP to coding contacts 120CT through its front contact 91 and back contact 95 of relay 5H, thereby transmitting a caution code to give signal 3 a caution indication for any following train. The energization of the home relay 3H by this caution code releases the directional stick relay 3S, and if there is no following train so that the home relay 4H is energized, then the transmitter relay 3CTP is governed by coding contacts 75CT over the normal circuit above described, and normal beat code conditions are at once restored in the middle track section 3-6T. When the east-bound train leaves the track section 5-8T in advance of the signal 5, the energization of the home relay 5H connects transmitter relay 6CTP to coding contacts 120CT over the normal energizing circuit prior to the deenergization of the directional stick relay 5S, so that the normal beat code conditions are maintained without interruption.

Considering now a west-bound train movement, the release of home relays 5H and 3H by tumble-down control provides an energizing circuit for the transmitter relay 3CTP readily traced on the drawings and including coding contacts 180CT and back contact 91 of relay 3H to give a clear indication for the intermediate signal 6. When this west-bound train passes signal 4 out of the middle track section 3-6T, the energization of the directional stick relay 4S provides a caution 75 code in the rear of this signal 4 to cause the intermediate signal 6 to indicate caution for a following train. If there is no following train, the energization of the home relay 6H by this caution code connects the transmitter relay 6CTP to coding contacts 120CT over the normal circuit above described, and this happens prior to the release of the directional stick relay 6S, thereby restoring beat code conditions in this middle track section without delay.

In this modified arrangement of Figs. 3A and 3B, since normal beat code conditions in the middle track 3-6T are immediately restored behind a train, the intermediate signals 3 and 6 are controlled to give a caution indication, and if not kept dark by an approach lighting arrangement such as illustrated, would display a caution indication inviting a back-up move. Accordingly, if the intermediate signals 3 and 6 are lighted behind a train, provision is preferably made in accordance with established practice to prevent these signals 3 and 6 from displaying an indication more favorable than stop while the directional stick relays 4S and 6S for the associated opposing signals are energized. In the present case, a west-bound train having passed the intermediate signal 4, it has caused the picking up of the directional stick relay 4S which opens back contact 98 and prevents the application of code pulses to the track section 4-4T in the rear of the train. This prevents the energization of the series relay 4SR by the train in the track section 4-4T, and thus prevents the picking up of the repeater relay 4SRP so that the signal 3 cannot be lighted in the rear of a train.

It may be pointed out here that sometimes under special conditions a train may enter the single track stretch at either end and then back out, as for example, in making a switching move-

ment; and in this case beat code conditions are restored in the middle track section 3-6T under different conditions. In the arrangement illustrated in Figs. 1B and 1C, when an east-bound train enters the single track stretch and then backs out, the energization of home relay 4H initiates transmission of code pulses at the 75 code rate east in the middle track section 3-6T in connection with code pulses at the 120 code rate then existing, so that the normal conditions are at once restored. In the case where west-bound train enters the single track stretch and then backs out, the relays 3H and 3D are de-energized by the tumble-down control and connect transmitter relay 3CTP to coding contacts 120CT; and when the train backs out and the home relay 5H is again reenergized, transmitter relay 6CTP is also connected to coding contacts 120CT. In other words, with the arrangement illustrated in Figs. 1B and 1C, opposing code pulses of the same 120 code rate are initially applied in opposite ends of the middle track section 3-6T, when a west-bound train enters the single track stretch and backs out. As previously discussed, although the coding contacts 120CT for the opposite ends of this track section nominally operate at the same code rate, in practice due to inherent variations in manufacture or by deliberate adjustment, these coding contacts do not have exactly the same rate, and will get out of step after a short time sufficiently to energize the track relay 3TR intermittently and pick up the relay 3H to discontinue temporarily the code pulses east, thereby allowing restoration of relay 3D to establish normal beat code conditions.

The arrangement of Figs. 3A and 3B, however, operates differently in case a train enters the single track stretch at either end and then backs out. In Figs. 3A and 3B, code pulses at different code rates are initially applied to opposite ends of the middle track section 3-6T under these conditions, and normal beat code conditions are immediately restored for both directions of train movement. For example, in the case of an east-bound train, the release of home relay 6H by tumble-down control provides a clear 180 code west toward signal 3, and when home relay 4H is again energized, code pulses of the 75 code rate are applied to restore normal beat code conditions without delay. In case a west-bound train enters and then backs out of the single track stretch, the deenergization of the home relay 3H by tumble-down control provides a 180 code toward the signal 6, and when home relay 5H is again energized and applies 120 code west, the beat code effect of these 180 and 120 codes at once energizes relay 3H to restore normal conditions.

The modification of Figs. 3A and 3B, illustrates, among other things, how the code rates for normal beat code conditions and for clear and caution signal controls may be selected in a way to obtain the desired results in various ways, and without adopting the specific features of operation characteristic of the specific embodiment of the invention shown in Figs. 1A to 1D inclusive.

Automatic control of a switch lock for an outlying switch.—The conventional single track railroad frequently has an outlying track switch connected with some one of the track sections of a single track stretch for connection with an industrial track or the like; and while train movement off of such outlying switch is subject to time-table rights or train order, perhaps supplemented by telephone communication with the train dispatcher, it is desirable in the interests

of safety to provide a switch lock for such outlying switch and suitable automatic control to prevent improper operation of the switch. Two arrangements for providing suitable automatic control for a switch lock are illustrated diagrammatically in Figs. 4 and 5 for an outlying switch SW, assumed to be connected with the middle track section 3-6T between the intermediate signals 3 and 6.

- 10 It is contemplated that the switch lock will be of the well-known manually operated type, in which the switch may be unlocked manually by hand for manual operation only if a lock relay or magnet is energized. Any specific form of a 15 switch lock of this type may be used with this invention; and the simplified arrangement diagrammatically illustrated in Fig. 4 is merely typical.
- Referring to Fig. 4, the switch points are locked 20 in the normal position against movement by the hand-throw device by the engagement of a lock plunger LP with a hole 130 in a lock rod LR connected to the switch points. This locking plunger LP may be lifted to unlock the switch by 25 a suitable handle 131, provided a lock relay or magnet L is energized to attract a movable lock dog 132 and permit movement of this handle 131. The locking plunger LP opens contacts 133 shown conventionally when moved to its unlocking position. It is contemplated that the operating handle 131 will be enclosed in a suitable casing 30 having a door (not shown) which when opened closes door contacts 134 shown conventionally. A spring-return push button PB and an indicating 35 lamp K are also accessible when the door is open; but the lock relay L and other operating parts are housed and protected against improper operation in accordance with recognized practice.

- With regard to the desired control of the lock 40 relay L, it can be appreciated that, when a train is approaching the outlying switch in either direction, the switch should be locked to prevent any careless or accidental attempt by a trainman to unlock and open the switch for a train to come 45 off of the switch into the main track. It can also be seen that, when such automatic control has been provided, a train desiring to operate the switch and enter the associated industrial track or the like, will exert the same locking effect in 50 approaching the switch as any other approaching train, so that some special release is required for train movement from the main track into the outlying switch. In the arrangement shown, this 55 special release is obtained by a means responsive to the presence of a train within a limited distance of the switch, specifically a short release track section having a track relay XTR and the track battery 135. Any train on this release track section can be readily seen by a trainman at the 60 switch, and it is assumed that no trainman will attempt to unlock and operate the switch for a train to come out while some other approaching train in plain sight occupies the release track section.

- 65 Considering the form of the invention shown in Fig. 4, the short release track section is provided by insulated joints 136 in one of the main track rails only, and a two-position magnetic stick type polar relay XSR is connected around 70 these insulated joints in series with a front contact 137 of the track relay XTR, a back contact 138 of the lock relay L, and the contacts 133 operated by the locking plunger. This electrical connection, including the relay XSR, together with

the continuous track rail, provides in effect an uninterrupted track circuit path for code pulses transmitted from opposite ends of the middle track section 3-6T, such code pulses passing through the winding of the relay XSR. In this connection, it is contemplated that the relay XSR and associated circuit connections will be of suitable low resistance to avoid adding unnecessary linear resistance into the coded track circuit.

Under normal conditions, with no train in the single track stretch approaching the switch in either direction, transmitter relays 3CTP and 6CTP at the opposite ends of the track section 3-6T are governed by coding contacts operating at different code rates to provide beat code pulses alternately in opposite directions; and assuming that these code pulses are of the same relative polarity, these current pulses flow through the relay XSR alternately in opposite directions and cause operation of its polar armature back and forth to operate suitable code responsive means, such as a decoding transformer and a relay XH as shown. When a train enters the single track stretch at either end, the code pulses in the corresponding direction are cut off by the tumble-down control in the usual way, leaving the relay XSR intermittently energized by current pulses flowing through its winding in the same direction, so that the polar armature of this relay remains stationary, and the relay XH becomes deenergized.

Assume now that there is a train on the industrial track or the like which is presumably authorized to open the switch and come out onto the main track. The trainman unlocks and opens the door for the switch lock case; and if there is no train coming in each direction, the relay XH is energized, and the door contacts 134 being closed, the indicating lamp K is lighted by a circuit from (+), through front contact 139 of relay XH, normally closed contact of push button PB, lamp K, back contact 140 of relay L, and door contacts 134, to (-). The lighting of the lamp K indicates that no train is approaching the switch; and the trainman then operates the push button PB to energize the lock relay L by a circuit from (+), through front contact 139 of relay XH, normally open contact of push button PB now closed, lock relay L, and door contacts 134, to (-). The energization of the relay L closes at its front contact 141, a stick circuit readily traced on the drawing through the door contacts 134; and consequently relay L remains energized until the switch lock is no longer being used and the door is closed to open the door contacts. The circuit for the lamp K is also preferably broken at the back contact 140 of the relay L, so that after release and restoration of the push button PB, the lamp K remains extinguished to show that relay L has been effectively energized, and also incidentally providing for the energization of relay L by its stick circuit independently of the resistance of the lamp K.

When the lock relay L has thus been energized to unlock the switch, it opens at its back contact 138 the electrical connection around the insulated joints 136 and prevents transmission of code pulses in either direction toward the intermediate signals 3 and 6, thereby putting these signals to stop and also the head-block signals 1 and 8 in the rear thereof by the regular tumble-down control. In other words, as soon as the lock relay L is energized and the switch lock is manually unlocked, all of the signals governing

train movement toward the switch are put to stop, as indicated diagrammatically in Fig. 2V.

After the lock relay L has been energized, the locking plunger LP may be raised by the handle 5 131 to unlock the switch in the regular way, and the points may then be opened by hand for the train in question to come out onto the main track, where it manifests its presence by shunting the coded track circuit or the track relay XTR to keep at stop the signals governing train movement toward the switch. When the train in question, after coming out onto the main track, passes the first intermediate signal 4 or 5 in its movement toward a passing siding, the associated directional stick relay 4S or 5S is energized, and coding is established for clearing the signals for following train movements the same as if this train entered the single track stretch at one end.

After the train has passed over the switch, a trainman is supposed to restore the switch SW to normal, lock the switch points by the locking plunger LP, and close the door; and if this is done, all of the parts are restored to the normal condition shown ready for some subsequent operation. However, if the trainman carelessly closes the door and drops relay L without again locking the switch, signals governing train movements toward the switch are held at stop, because the lock rod LR maintains the circuit connection around the insulated joints 136 open at contacts 133. Such a condition would bring the carelessness of the trainman to the attention of others to serve as a check against such faulty action. In this connection, it is assumed that the lock rod LR will be provided with only one hole 130 for the locking plunger LP, so that this locking plunger cannot assume its locking position until the switch points are in the normal position. The door contacts 134 not only avoid unnecessary lighting of the indicating lamp K when the switch lock is not being used, but also keep the lock relay L energized so that if the trainman should carelessly leave the door open, the signals governing train movement toward the switch are kept at stop by reason of open back contact 138.

With the embodiment of the invention shown in Figs. 1A to 1D inclusive, the switch lock may be released after a west-bound train has passed out of the middle track section 3-6T beyond the intermediate signal 4, since normal beat code conditions are restored in this track section behind such train as illustrated in Fig. 2H; but the switch lock cannot be released after passage of an east-bound train until that train has left the single track stretch, because there are no code pulses in both directions in the middle track section 3-6T until this happens, as can be seen by comparing Figs. 2D and 2E. With the modified arrangement of Fig. 3 used for the middle track section, however, as previously explained, normal beat code conditions are established behind an east-bound train as well as a west-bound train; and consequently the switch lock may be released as soon as such a train has passed beyond the intermediate signal 4 or 5.

If the trainman for a train on the outlying switch, due to some misunderstanding of train orders or otherwise, should attempt to use the switch lock at a time when there is a train approaching the switch in either direction, under these conditions the relay XH is deenergized, the indicating lamp K is extinguished, and the lock relay L cannot be energized by operation of the

push button PB. In short, the switch is fully protected against improper operation.

Considering now the case where a train approaching the switch on the main track is required to open this switch to enter the industrial track or the like, when this train advances into the release track section and stops, the dropping of the track relay XTR and closing of its back contact 142 provides an energizing circuit for the indicating lamp K and the lock relay L to permit the switch to be unlocked and opened because relay XH is already dropped away due to the presence of the train. When the switch is thereafter restored to normal, normal conditions are established for subsequent train movement in either direction. The release track section is preferably short and located on the facing point side of the switch points close to the switch, but far enough away to enable an east-bound train to pull into the release track section and then proceed after the switch has been opened without backing up. It will be apparent that a west-bound train must pull past the switch points in order to move over the switch when open, and hence can be moved into a position to shunt the release track section without difficulty. The presence of a single car or locomotive on the release track section stops code transmissions both ways by dropping the track relay XTR and opening its front contact 137.

Fig. 5 illustrates a modified arrangement for the automatic control of a switch involving the same principles, but providing for relaying or repeating the code pulses around the insulated joints forming the release track section adjacent the switch. These insulated joints 150, which may be located in the staggered relation in the opposite track rails as indicated or arranged in series in both track rails, in effect divide the track section between the opposing signals 3 and 6 into two track sections designated for convenience as 3-XT and 6-XT. The short release track section between the insulated joints 150 is provided with the same track relay XTR and track battery 135 as in the arrangement of Fig. 4.

In the modification of Fig. 5, track relays 3ATR and 6ATR are provided for the two track sections 3-XT and 6-XT on opposite sides of the insulating joints 150, and each of these track relays when energized acts to disconnect the other track relay from the track rails and apply a battery potential, providing the release section track relay XTR is energized, the lock relay L is de-energized, and the locking plunger LP is in its locking position. The track relay 3ATR, for example, is connected across the track rails of the track section 3-XT by an electrical connection which may be traced from the lower track rail, contacts 151 of the locking plunger LP, back contact 152 of lock relay L, back contact 153 of track relay 6ATR, track relay 3ATR to the upper track rail. When the track relay 3ATR is energized, it applies a battery potential across the rails of the adjacent track section 6-XT by an electrical connection which may be traced from the lower track rail through back contact 154 of lock relay L, contacts 155 of the locking plunger LP, front contact 156 of the track relay ATR, track battery 157 and front contact 158 of track relay XTR to the upper track rail.

The track relays 3ATR and 6ATR, together with their associated track batteries, act to repeat code pulses in both directions past the insulated joints 150; and except for the fact that these track relays add one more relay operating time in apply-

ing and cutting off the code pulses received at one signal location from the other signal location, the code pulses are repeated in either direction alone, or in both directions under beat code conditions, with the same operating results as in the case of a single track section.

Each track relay 3ATR and 6ATR energizes a corresponding slow release front contact repeater relay 3ATP and 6ATP; and it can be readily seen that under normal beat code conditions, when there are no trains in the single track stretch approaching the switch, both of these repeater relays are energized and close their front contacts 159 and 160 to provide for lighting the indicating lamp K and energization of the lock relay L in the same way previously described in connection with the energization of relay L in Fig. 4. It is not necessary to provide a decoding transformer or equivalent means to detect coding operation of these track relays 3ATR and 6ATR for release of the electric lock, since the steady energization of either of these track relays by foreign current or the like, although maintaining its associated repeater relay energized, prevents energization of the other track relay and drops its repeater relay.

The modified arrangement of Fig. 5 otherwise operates in the same manner as in the arrangement shown in Fig. 4 to provide an automatic control for the switch lock and release of this switch lock behind a train.

Highway crossing signal control.—Highway crossings on single track railroads are commonly protected by some form of a signal or gate automatically controlled by a train approaching the crossing in either direction; and where, as in the system of this invention, the indications of the wayside signals are governed by coded track circuits, it is desirable to provide for the automatic control of highway crossing signals by coded track circuits and without the use of line wires.

One arrangement for providing automatic control of highway crossing signals in a coded track circuit system for train movement in both directions is illustrated in Figs. 6A, 6B and 6C for a highway crossing located between the pairs of intermediate signals 3, 4, and 5, 6; and the explanatory diagrams of Figs. 7A to 7F inclusive illustrate diagrammatically the direction and rate of coding and the condition of certain relays for different positions of an east-bound train approaching and leaving the highway crossing. It is to be understood that this highway crossing control can be used with either the form of the invention shown in Figs. 1A-1D or as modified by Figs. 3A and 3B.

The typical automatic control of a bell, flashing light signal, gate, or equivalent protective device at a highway crossing involves an approach track section of such length that the protective device is set into operation upon the approach of a train a reasonable clearance time prior to the arrival of the train at the crossing, the length of this approach track section being in the order of 2000 feet for the generally accepted clearance time of twenty seconds and the usual maximum speed of trains. In the case of a single track railroad, where a train may approach the highway crossing from either direction, there is an approach track section on each side of the crossing; and an interlocked relay or equivalent means governed by these approach track sections is employed to cause operation of the protective device at the crossing when an approach track section is occupied by a train travelling toward the cross-

ing, but not by a train travelling away from the crossing.

It is contemplated that this conventional arrangement of two approach track sections and an interlocked relay for highway crossing signal control will be employed in the present invention. While highway crossings may be located of course at any point with respect to the passing sidings and signal locations on a single track railroad, in the particular arrangement illustrated, it has been assumed that the highway crossing will be located at the appropriate control distance from the location of the intermediate signals 3 and 4, so that the track section ET between these signals and the insulated joints 170 at the crossing constitute the east approach track section for the crossing. Also, in order to illustrate how cut-sections may be employed in connection with the control of the highway crossing signal, it is further assumed, as is usually the case, that the block length between the opposing signals 3 and 6 is greater than the length of the two approach track sections, so that insulated joints 171 are required to define the west approach track section WT, leaving another track section, conveniently designated 3-6T, between these insulated joints 171 and the location of signal 6. The same operating principles and general circuit organization disclosed for this assumed arrangement may be readily adapted for any location of a highway crossing with respect to the wayside signals.

Referring to Figs. 6A, 6B and 6C, the coding equipment for the locations of the pairs of intermediate signals 3, 4, and 5, 6 is generally the same as previously described, more particularly as in connection with the modification of Figs. 3A and 3B, with the exception that a special control is employed for the home relays 3H and 6H for the opposing intermediate signals 3 and 6 governing train movement toward the highway crossing. Considering the home relay 3H in Fig. 6A as typical, this relay instead of being energized by the coding operation of the associated track relay 3TR at any code rate and under beat code conditions, is provided with two windings and two energizing circuits, one circuit through the upper winding constituting an initial energizing or pick-up circuit, and the other circuit through the lower winding and a front contact 172 of the relay 3H constituting a maintaining or stick circuit. The upper winding of the relay 3H is connected to a tuned decoding circuit and rectifier in the usual way for providing energizing current for the relay 3H when the track relay 3TR is operated at the 120 code rate; and the maintaining circuit through the lower winding and front contact 172 is energized directly from the decoding transformer in the usual way, so that the relay 3H, after being initially energized in response to 120 code rate, is thereafter maintained energized so long as the associated track relay 3TR is intermittently energized at recurrent intervals regardless of the particular rate of such energization. The distant relays 3D and 6D for these signals 3 and 6 are energized in the usual way by decoding apparatus in response to the clear 180 code rate.

Also, the track relay 3TR energizes a front contact repeater relay 3TRP, which in the particular arrangement shown is connected in series with the upper half of the decoding transformer. This repeater relay 3TRP is made sufficiently slow releasing by any well-known expedient, such as a shunting rectifier or the like, to maintain its armature in the attracted position during the

periods of deenergization of the track relay 3TR when operated at the lowest code rate or under beat code conditions.

The coding apparatus at the highway crossing 5 for the east and west approach track sections ET and WT are alike; and considering that for the track section ET as typical, a transmitter relay ECTP is arranged to connect a track battery 173 and a code following track relay ETR alternately across the track rails in the usual way. The coding operation of the track relay ETR at any code rate energizes a relay EH, and at the clear 180 code rate a relay ED, these relays EH and ED being in effect home and distant relays, although not controlling the indication of any signal.

Also, an additional special track relay EXR, conveniently termed a shunt track relay, is connected across the track rails of the track section 20 ET adjacent the crossing. This shunt relay EXR is energized at times from the track battery 173 in multiple with the track relay 3TR at the other end of the track section ET, and at other times in multiple with the track relay ETR from the track battery 174 at the signal 3 when code pulses are transmitted east in the track section ET. In other words, the shunt track relay EXR is sometimes energized from the track battery at the same end of the track section, as well as by the track battery at the opposite end of the track section.

Generally speaking, the effect of the wheel shunt of a train in a track section to cause the release of a track relay, or prevent its energization 35 in the case of a coded track circuit, is due to the reduction in inter-rail potential caused by the increase in current through the usual limiting resistance in series with the track battery or other source of current supplying energy to the 40 track section; and for relatively short track sections, such as suitable for approach control of highway crossings, a track relay at the same end of the track section at which the track battery is applied, such as the shunt relay EXR, may be 45 effectively shunted by a train at any point in the track section, assuming of course suitable track bonding and appropriate resistances and voltages. In short, the shunt track relay EXR will respond to the entrance of an east-bound train 50 into the approach track section ET, when this track relay is intermittently energized by the track battery 173 by operation of the transmitter relay ECTP, as well as when this relay EXR is intermittently energized by the track battery 55 174 at the signal 3 by operation of the transmitter relay 3CTP.

In this connection, it can be seen that, when the transmitter relay ECTP drops after having been energized to connect the track battery 173 to the shunt track relay EXR, then the code following track relay ETR is directly connected across the shunt track relay EXR, and the energy stored in this shunt track relay tends to discharge through the winding of the code following track relay ETR in multiple with the ballast resistance of the track section. Under unfavorable conditions, such impulse voltages might cause improper energization of the track relay ETR and cause it to be improperly coded in the absence of legitimate code pulses from the opposite end of the track section. As previously noted, code following track relays, such as the track relay ETR, are preferably of the two-position biased polar type; and if the track batteries at the 70 opposite ends of the track section ET are arranged

as shown to energize the track rails with the same polarity, then the discharge voltage of the shunt track relay EXR when energized from its associated battery 173 is in a direction to operate the armature of the track relay ETR to its biased position. Thus, the track relay ETR is protected against improper coding operation by impulse voltages from the shunt track relay EXR.

Each of the shunt or multiple track relays EXR and WXR at the highway crossing energize slow-release front contact repeater relays EXRP and WXRP by obvious circuits; and these repeater relays in turn govern the energization of the two coils or windings of an interlocked relay of the usual type governing the operation of the highway crossing signal.

Referring to Figs. 6B and 6C, code pulses in either direction, or in both directions under beat code conditions, in the track sections WT and 3-6T are repeated or relayed past the insulated joints 171 by the operation of interlocked track relays 3ATR and 6ATR in the same manner as previously discussed in connection with the control of the switch lock shown in Figs. 4 and 5. It can be readily seen that the track relay 3ATR, for example, may be energized by a code pulse east in the track section WT, providing the other track relay 6ATR is not energized by a code pulse west in the other track section 3-6T, and can connect a track battery across the track rails of the track section 3-6T to repeat or relay this code pulse east in the track section WT into the track section 3-6T.

Under the normal conditions shown in Figs. 6A, 6B and 6C beat code conditions exist in each of the track sections as indicated in the explanatory diagram of Fig. 7A. Referring to Fig. 6A, and disregarding for the present the conditions under which the home relay 3H became energized, transmitter relay 3CTP is connected under normal conditions with no trains present to coding contacts 75CT by a circuit from (+), through back contact 175 of track relay 3TR, coding contacts 75CT, front contact 176 of home relay 3H, front contact 177 of home relay 4H, transmitter relay 3CTP, and back contact 178 of directional stick relay 3S, to (-).

Transmitter relay ECTP for the other end of the track section ET is connected under normal conditions to coding contacts 120CT by a circuit from (+) through back contact 182 of track relay ETR, coding contacts 120CT, back contact 183 of distant relay WD, front contact 184 of home relay WH, relay ECTP, to (-). Transmitter relay WCTP for the end of the west approach track section WT adjacent the crossing, is likewise connected under normal conditions to coding contacts 120CT by a circuit corresponding to that described for the transmitter relay ECTP; and these code pulses forming a part of a beat code are relayed past the insulated joints 171 in Fig. 6B into the track section 3-6T. The transmitter relay 6CTP at the signal 6 is connected to coding contacts 75CT by a circuit from (+), through back contact 185 of track relay 6TR, coding contacts 75CT, front contact 186 of home relay 6H, front contact 187 of home relay 5H, relay 6CTP, and back contact 188 of directional stick relay 6S, to (-). These code pulses east in the track section 3-6T also form a part of a beat code and are relayed past the insulated joints into the adjacent west approach track section WT.

Under these normal conditions, it can be seen that the shunt track relays EXR and WXR at

the crossing are energized under these beat code conditions normally existing by code pulses applied alternately at opposite ends of the corresponding track sections; and consequently, both of the repeater relays EXRP and WXRP are energized to maintain the highway crossing signal inactive.

Considering now a typical operation for an east-bound train movement, when this train enters the single track stretch and deenergizes the home relay 4H to put the opposing intermediate signal 4 to stop in the regular way, the opening of the front contact 171 of this relay 4H opens the normal energizing circuit for the transmitter relay 3CTP and stops its coding operation. Consequently, coding operation of the track relay ETR ceases and home relay EH is deenergized to open at its front contact 189 the normal energizing circuit for the transmitter relay WCTP, thereby stopping transmission of code pulses east in the track sections WT and 3-6T, whereupon coding operation of the track relay 6TR ceases and home relay 6H is deenergized to put the opposing signal 6 to stop and also continue the tumble-down control for the opposing head-block signal 8.

During this tumble-down control, the transmitter relay ECTP at the crossing continues in operation to intermittently energize the shunt track relay EXR from the track battery 173; and similarly, transmitter relay 6CTP at signal 6 continues in operation to transmit code pulses west in the west approach track section WT and intermittently energize the shunt track relay WXR. Thus, the highway crossing signal is maintained inactive.

When the home relay 6H for signal 6 is deenergized by the tumble-down control, it connects through its back contact 186 and back contact 190 of relay 6TRP the transmitter relay 6CTP to coding contacts 180CT, so that code pulses at the 180 code rate are transmitted west in track section 3-6T and relayed into track section WT, where the operation of the track relay WTR at the high clear code rate causes energization of distant relay WD to close its front contact 183 and connect the transmitter relay ECTP to coding contacts 180CT. This changes the code rate of the code pulses transmitted west in the track section ET to the 180 clear code rate, and energizes distant relay 3D to cause signal 3 to display a clear indication.

These conditions just described are diagrammatically indicated in Fig. 7B.

Assume now that the east-bound train in question passes the signal 3 into the east approach track section ET, as indicated in Fig. 7C. The entrance of this train prevents the energization of the shunt track relay EXR at the crossing, and its repeater relay EXRP drops to deenergize one winding of the interlocked relay and start the crossing signal or equivalent protective device into operation.

In the type of signaling system illustrated, there is no coding east in the track section 1-4T in the rear of signal 3, for reasons previously explained, and this would likewise be true in a coded track circuit signaling system for single track railroads of other types if there should be a following train, so that coding east in the approach track section ET cannot be used to stop operation of the crossing signal, when this track section becomes vacated. Accordingly, when the east-bound train in ques-

tion passes beyond the insulated joints 170 at the crossing as indicated in Fig. 7D, coding in the track section ET for the control of the highway crossing signal is artificially applied, so to speak.

In the arrangement shown, when the relay WH is deenergized by the train, the transmitter relay ECTP is connected to coding contacts operating at a low code rate, preferably different from the 75 code rate, such as coding contacts 60CT by a circuit which may be traced from (+), through the back contact 182 of track relay ETR, back contact 191 of home relay EH, coding contacts 60CT, back contact 184 of home relay WH, and transmitter relay ECTP, to (-). In this way, the transmitter relay ECTP is operated to apply the track battery 173 at intervals to energize the shunt track relay EXR, and in turn its repeater relay EXRP to stop operation of the crossing signal in the rear of the east-bound train. The track relay 3TR at the signal 3 is also operated by these code pulses thus artificially applied; but these code pulses are not at the 120 code rate required to initially energize the home relay 3H, and hence the signal 3 remains at stop.

When the east-bound train in question enters the west approach track section WT as shown in Fig. 7D, the transmitter relay WCTP for this track section is likewise connected to coding contacts 60CT by a circuit similar to the one just described, and including back contacts 192 and 189 of the relays WH and EH, so that when this train leaves this west approach track section WT, as indicated in Fig. 7E, code pulses of the 60 code rate are transmitted east in this track section, and the shunt track relay WXR and its repeater relay WXRP are again energized, restoring normal conditions at the crossing. In this connection, it can be readily seen that if the train in question for some reason should happen to back up into the west approach track section WT, the shunt track relay WTR is deenergized and the crossing signal operated.

Considering now the operation when the east-bound train in question passes beyond the intermediate signal 5, the code pulses at the special 60 code rate following this train in the track section 3-6T may cause intermittent energization of the track relay 6TR, but home relay 6H remains deenergized. The directional stick relay 5S associated with the signal 5 is energized in the regular way, as previously explained, by the east-bound train and provides code pulses west at the 75 code rate in the track section 3-6T, and by repeater action into the track section WT; and under these conditions, analogous to beat code conditions, relay WTR is intermittently energized, thereby energizing the home relay WH and opening its back contact 192 to stop further transmission of code pulses at the special 60 code rate. The energization of the home relay WH also closes its front contact 184 to establish the normal energizing circuit for the transmitter relay ECTP, and cause its operation at the 120 code rate. A reception of the code pulses at the 120 code rate energizes the home relay 3H to cause signal 3 to indicate caution for any following train. Also, energization of the home relay 3H applies code pulses of the 120 code rate west in the track section 1-4T, thereby clearing the head-block signal 1 and restoring beat code conditions in this end track section to energize home relay 4H and restore normal beat code con-

ditions in the track section ET. Coding operation of the track relay ETR at the highway crossing energizes home relay EH to establish the normal energizing circuit for the transmitter relay WCTP and restore normal beat code conditions in the other track sections WT and 3-6T.

These conditions are indicated diagrammatically in Fig. 7F, and in this Fig. 7F the symbols representing the restoration conditions should be read from left to right for each of the track sections ET and WT.

When beat code conditions are established in the track section 3-6T as just described, at the time the code pulses at the 120 rate are first transmitted east in this track section, the transmitter relay 6CTP is already operating at the 75 code rate, so that the track relay 6TR cannot be operated uniformly at the 120 code rate required to initially energize the home relay 6H. Consequently, the intermediate signal 6 remains at stop behind the east-bound train in question and prevents any back-up move under a favorable signal indication. The intermittent energization of the track relay 6TR, however, energizes its repeater relay 6TRP and opens its back contact 190; and when the train in question leaves the end track section 5-8T in advance of the signal 5 and the home relay 5H is energized, coding operation of the transmitter relay 6CTP previously maintained due to the energization of the directional stick relay 5S and closure of front contact 193, stops temporarily, the back contact 190 of the repeater track relay 6TRP and the front contact 186 of the home relay 6H being both open. This cessation of operation of the transmitter relay 6CTP allows coding operation of the track relay 6TR without interference at the 120 code rate, whereupon the relay 6H is energized to close its front contact 186 and establish the normal circuit for operating transmitter relay 6CTP at the 75 code rate. The cessation of code pulses west in the track section 3-6T is only momentary during the time required for the initial energization of the home relay 6H; and this time interval is too short for the home relay 6H to drop and initiate a tumble-down control. As soon as the home relay 6H is initially energized, it is maintained energized under beat code conditions by the holding circuit through its lower winding.

The operation of the highway crossing signal for a west-bound train movement involves similar circuits and sequences of operations just described for an east-bound train movement; and a detail discussion of the operation for a west-bound train movement is not necessary.

One significant operating characteristic of this arrangement for highway crossing signal control is that the shunt track relay for each approach track section adjacent the crossing and governing the highway crossing signal is energized at times by code pulses at code rates suitable for controlling the indications of the wayside signal governing train movement into the stretch of track including the crossing, and is also energized at other times behind a train to stop operation of the crossing signal by a special control code which does not clear said wayside signal. It can be seen that this operating principle is not limited to the particular form of automatic block signaling system disclosed, and may be readily applied to other types of coded track circuit signaling systems for both single and double track railroads. For example, this broad principle has been disclosed for use with double track railroads

in my copending application entitled "Coded track circuit signaling systems" and filed of even date herewith, and no claim is made herein to any subject matter disclosed in that application. The specific arrangement disclosed is specially adapted for a system of the beat code type used for single track railroads, and can be employed without change in such a system of the beat code type using centralized traffic control in the manner disclosed, for example, in the prior application of Judge, Ser. No. 455,922, filed August 8, 1942.

Various other modifications and adaptations not illustrated or described may be made in the construction and arrangement of parts and circuits illustrated without departing from the invention; and it is to be understood that the specific embodiments and modification of the invention illustrated are merely typical and illustrative of the principles and mode of operation of the invention.

What I claim is:

1. In a coded track circuit signaling system for railroads, the combination with a track section having a signal at one end governing train movement into said track section, a code following track relay and a transmitter relay for the end of said track section adjacent said signal, means for at times transmitting code pulses toward said signal at a caution or a clear code rate, signal control means initially rendered effective in response to the coding operation of said track relay at a clear code rate only to cause said signal to indicate clear, said signal control means when effective initiating operation of said transmitter relay at a code rate different from said clear code rate to establish beat code conditions, and means for maintaining said signal control means effective so long as said track relay is intermittently energized at recurrent intervals regardless of the particular rate of such energization, whereby beat code conditions normally existing in said track section are not established after said signal has been put to stop until code pulses at the clear code rate have been received without interference to cause said signal to indicate clear, and such clear indication is maintained until all transmission of code pulses toward that signal is stopped.

2. In a coded track circuit automatic block signaling system for single track railroads, a stretch of single track between the ends of passing sidings divided into track sections and having a head-block signal at each end governing train movement into the stretch, a code following track relay at each end of said stretch, signal control means associated with each head-block signal for causing that signal to indicate clear or caution in response to the coding operation of the corresponding track relay by code pulses at a clear or caution code rate, means for at times transmitting code pulses toward said signal at a caution or clear code rate, code transmitting means for each head-block signal operable when effective to apply code pulses at a code rate different from the clear code rate to the track rails at the corresponding end of said stretch to establish beat code conditions with such clear code, means governed by each signal control means for rendering the corresponding code transmitting means effective only when code pulses at the clear code rate are received, whereby a beat code condition is not established until a clear control for the associated head-block signal has been transmitted, and means for maintaining the clear indication of each head-block signal when once established

so long as the corresponding track relay is intermittently energized.

3. In a coded track circuit automatic signal system for a stretch of single track divided into track sections and having a head-block signal at each end governing train movement into said stretch, intermediate signals at the adjacent ends of said track sections for governing train movement in opposite directions through said stretch, means including a code following track relay for governing the indications of each signal, code transmitting means for said track sections including intermittently operated coding contacts and normally acting to energize the track rails at the opposite ends of the same track section with driven code pulses at different intervals to energize intermittently both track relays of that track section, means associated with each intermediate signal and responsive to the cessation of the intermittent energization of the corresponding track relay for cutting off transmission of code pulses in an adjacent track section toward the next signal in the rear, a distant relay for each head-block signal energized by the coding operation of the associated track relay at the clear code rate only for causing its head-block signal to indicate clear and thereafter render the associated code transmitting means effective to restore normal coding conditions in the corresponding end track section, and means for maintaining each distant relay energized after once energized while the associated track relay is intermittently energized at recurrent intervals regardless of the particular rate of such energization.
4. In a coded track circuit automatic block signaling system for single track railroads, a stretch of single track between the ends of passing sidings divided into track sections and having a head-block signal at each end governing train movement into the stretch, intermediate signals at intervals in the stretch governing train movement in opposite directions, code transmitting and receiving means associated with each end of each track section and normally acting to provide code pulses at intervals in both directions in said track section, said means acting in response to the entrance of a train into said stretch to stop transmission of code pulses in a direction away from that train toward each end of the stretch, means responsive to the direction of train movement through said stretch for independently governing said code transmitting means to provide code pulses at the caution and clear code rates in track sections in the rear of such train to clear signals for following train movements, and signal control means associated with each head-block signal for causing that signal to indicate clear in response to the reception of code pulses at the clear code rate only and thereafter applying code pulses in the opposite direction to restore normal coding conditions in the corresponding end track section, said signal control means maintaining a clear indication of its head-block signal once established so long as code pulses are being received at that signal regardless of their rate.
5. In a coded track circuit automatic block signaling system, a stretch of single track divided into track sections and having a head-block signal at each end and intermediate signals at intervals for governing train movement into and through said stretch in opposite directions, means including a code following track relay for each end of each track section for governing the indications of the corresponding signal in accordance with the rate of the coding operation of said track relay, code transmitting means including intermittently op-

erated coding contacts for each end of said track section, said code transmitting means for the opposite ends of the same track section being normally operated while the stretch is not occupied by coding contacts operated at different code rates to provide beat code pulses in both directions in that track section, said code transmitting means at the intermediate signals transmitting code pulses toward the head-block signals being governed by contacts operating at the clear code rate, and signal control means for each head-block signal for rendering the associated code transmitting means effective to provide a beat code in the corresponding end track section only after code pulses at the clear code rate have been received to cause that signal to indicate clear, said signal control means acting to maintain a clear indication of its associated head-block signal once established so long as the associated track relay is intermittently energized at recurrent intervals regardless of the rate of such energization.

6. In a coded track circuit signaling system for a stretch of single track divided into track sections and having a head-block signal at each end governing train movement into the stretch and intermediate signals at intervals governing train movement in opposite directions through said stretch, means including a code following track relay for governing the clear and caution indications of each signal in accordance with the rate of the coding operation of that track relay, code transmitting means for the opposite ends of each track section including coding contacts intermittently operable at different code rates, certain of said code transmitting means being normally governed by coding contacts operating at the clear code rate while the stretch is not occupied to provide code pulses in one direction in each end track section toward the corresponding head-block signal, tumble-down means for rendering said code transmitting means applying code pulses to the track section in the rear of each intermediate signal effective only if code pulses are being transmitted toward that signal, whereby the entrance of a train into said stretch at either end stops transmission of code pulses in the opposite direction in each track section to prevent clearing of all opposing signals, and directional means for each intermediate signal for governing the code transmitting means for the track section in the rear thereof to provide code pulses at the caution code rate independently of said tumble-down means while the track section in advance of that signal is occupied by a train moving in the direction of traffic governed by that signal.

7. In a coded track circuit automatic block signaling system for a stretch of single track divided into track sections and having signals at the ends of said track sections governing train movement into and through said stretch in opposite directions, code transmitting means for said track sections including coding contacts intermittently operated at predetermined code rates and normally acting while the stretch is not occupied to apply code pulses at different intervals to both ends of each track section, a code following track relay for each end of each track section normally energized intermittently under said normal coding conditions in that track section, said code transmitting means for one end of certain track sections being normally governed by coding contacts operating at the clear code rate and the other code transmitting means for the opposite ends of said certain track sections being normally governed by coding contacts

operating at a different code rate, signal control means for governing the indications of each signal and including a distant relay energized only if the associated track relay is operated at the clear code rate, means for rendering each of said code transmitting means for said opposite ends of said certain track sections effective to apply pulses at said different code rate only if the corresponding distant relay is energized, and means for maintaining each of the last mentioned distant relays energized after once energized so long as the associated track relay is intermittently energized.

8. In a coded track circuit automatic block signaling system of the character described, the combination with a stretch of track including a track section having a signal at one end governing train movement into said track section, a distant relay acting when energized to cause said signal to indicate clear, means including a code following track relay and decoding means for energizing said distant relay in response to the coding operation of said track relay at a predetermined clear code rate only, a home relay energized by the intermittent energization of said track relay at recurrent intervals regardless of the particular rate of such energization, a stick circuit for said distant relay including a front contact thereof closed while said home relay is energized, a transmitter relay for applying code pulses to the track rails of said track section adjacent said signal, an operating circuit for said transmitter relay including a front contact of said distant relay and coding contacts operating at a code rate different than said clear code rate, and circuit means effective only if said home relay is deenergized for operating said transmitter relay at a code rate dependent upon the presence of a train in the portion of said stretch in the rear of said signal.

9. In a coded track circuit signaling system for a stretch of single track having a signal at each end governing train movement into said stretch, a code following track relay for each end of said stretch, means including a distant relay and a home relay for governing the indications of each signal, said home relay being energized by intermittent energization of the corresponding track relay at the recurrent intervals regardless of the particular rate, said distant relay being energized only if the corresponding track relay is energized at intervals corresponding with a clear code rate, a directional stick relay for each signal energized only by train movement in the direction of traffic governed thereby and maintained energized while the corresponding home relay is deenergized, code transmitting means for each end of the stretch operable to transmit code pulses toward the other end only if either the corresponding home relay, distant relay and directional stick relay are all deenergized or said distant relay is energized, and means for maintaining said distant relay energized after it has once been energized while said home relay is energized.

10. In a coded track circuit automatic block signal system for single track railroads, a stretch of single track having a head-block signal at one end governing train movement into said stretch and an intermediate signal governing train movement toward said head-block signal, a distant relay acting when energized to cause said head-block signal to indicate clear, means including a code following track relay and decoding means for energizing said distant relay only when code

pulses at a predetermined clear code rate are received at said head-block signal, means for transmitting code pulses at a clear or caution code rate toward said head-block signal, code transmitting means for transmitting code pulses from said head-block signal toward said intermediate signal, means effective only if said distant relay is energized for governing operation of said code transmitting means at a code rate different from said clear code rate and thereby establish beat code conditions in the track section between said signals, means for maintaining said distant relay energized after once energized so long as said track relay is intermittently energized at recurrent intervals, and means effective while no code pulses are being received at said head-block signal for causing said code transmitting means to send code pulses toward said intermediate signal for governing its indication in accordance with traffic conditions.

11. In a coded track circuit automatic block signal system of the absolute-permissive type for single track railroads, the combination with a head-block signal and an entering signal at the end of a stretch of single track adjacent a passing siding for governing train movement into and out of said stretch, code responsive means including a code following track relay and home and distant relays for governing the indications of said head-block signal, decoding means for energizing said distant relay only when said track relay is intermittently energized at a predetermined clear code rate, means for energizing said home relay by the intermittent energization of said track relay at recurrent intervals regardless of the particular rate of such energization, means for maintaining said distant relay energized after once energized while said home relay is energized, said head-block signal indicating caution when the home relay alone is energized and clear when both the home relay and the distant relay are energized, a transmitter relay operable to apply code pulses to the track rails of said stretch of said adjacent head-block signal, coding contacts intermittently operated at a code rate different from the clear code rate, circuit means for operatively connecting said transmitter relay with said coding contacts only while said distant relay is energized, and means effective if said home relay and said distant relay are both deenergized for independently operating said transmitter relay at a code rate determined by traffic conditions in advance of said entering signal.

12. In a coded track circuit automatic block signaling system for a single track railroad, the combination with a stretch of single track between the ends of passing sidings divided into track sections and having a head-block signal at each end governing train movement into the stretch, code transmitting means for each of said track sections including intermittently operated coding contacts and normally active while the stretch is not occupied to apply code pulses at different intervals to the opposite ends of the same track section, each of said code transmitting means for transmitting code pulses toward a head-block signal acting only if a stretch is not occupied by a train moving toward that signal to apply code pulses at the clear code rate, a distant relay for each head-block signal acting when energized to cause that signal to indicate clear and also render the associated code transmitting means effective to restore normal coding conditions in the corresponding end track sections, decoding means for energizing each of said

distant relays only when code pulses of the clear code rate are received at the signal, and means responsive to the cessation of code pulses normally being received at a head-block signal for governing the operation of the associated code transmitting means independently of the energized condition of the corresponding distant relay and thereby provide code pulses in the corresponding end track section at a code rate determined by traffic conditions in a portion of track in the rear of said head-block signal.

13. In a coded track circuit signaling system for a stretch of track divided into track sections and having signals at intervals governing train movement into and through said stretch in opposite directions, code transmitting means including intermittently operated coding contacts for each end of each track section, said code transmitting means for the opposite ends of the same track section being normally governed by coding contacts operated at different code rates to provide beat code pulses at intervals in both directions over the track rails of that track section, a directional stick relay for each signal energized by train movement in the direction of traffic governed by that signal and maintained energized while the track section in advance of that signal is occupied, and means for rendering each of said code transmitting means ineffective while the corresponding directional stick relay is energized.

14. In a coded track circuit automatic block signaling system for single track railroads, a stretch of single track having opposing intermediate signals at the opposite ends of a track section, a code following track relay and a home relay associated with each signal, said home relay being energized in response to the intermittent energization of said track relay at recurrent intervals regardless of the particular rate of such energization, code transmitting means for the opposite ends of said track section normally governed while the corresponding home relay is energized by coding contacts operating at different code rates to provide code pulses at intervals in both directions in said track section, means effective when the home relay for a signal is deenergized for governing the energization of the corresponding code transmitting means at a code rate determined by traffic conditions in the portion of said stretch of track in the rear of that signal, a directional stick relay for each signal energized by train movement in the direction of traffic governed thereby and maintained energized while said track section in advance of that signal is occupied, and means for rendering each of said code transmitting means ineffective while the corresponding directional stick relay is energized.

15. In a coded track circuit signaling system for a stretch of track divided into track sections and having signals at the ends of said track sections governing train movement in opposite directions, code transmitting means for the opposite ends of each track section normally governed by coding contacts operating at different code rates to provide beat code pulses in both directions in that track section, tumble-down means responsive to the entrance of a train into said stretch at either end for rendering ineffective all of those code transmitting means normally acting to send code pulses toward the other end of said stretch and thereby put to stop all opposing signals, directional means associated with each intermediate signal and energized only by train

movement in the direction of traffic governed by that signal for providing code pulses for the track section next in the rear independently of the control of said tumble-down means and thereby permit clearing of signals for following train movements, and means associated with each of said directional means and effective while energized to render ineffective the associated code transmitting means, whereby the energization of a directional means to clear a signal for following train movements prevents transmission of code pulses in a direction toward the opposing signals.

16. In a coded track circuit signaling system for a stretch of track divided into track sections having signals at intervals governing train movement into and through said stretch, means including a code following track relay for governing the indications of each signal in accordance with the code rate of pulses transmitted over the track rails toward that signal, code transmitting means associated with the ends of said track sections and normally governed at the clear code rate for one end of each track section and at the caution code rate for the other end of that track section, whereby a beat code is normally provided in each track section for the intermittent energization of both track relays of that track section, tumble-down means for preventing transmission of code pulses in each track section toward either end of the stretch unless code pulses are being transmitted in a corresponding direction in an adjacent track section, directional means acting while a track section in advance of an intermediate signal in the stretch is occupied by a train moving in the direction of traffic governed thereby to supply code pulses at the caution code rate to the track section in the next in the rear independently of said tumble-down means, and means including said directional means for preventing the operation of those code transmitting means governed at the caution code rate until code pulses at the clear code rate are received at the corresponding end of the associated track section.

17. In a coded track circuit automatic block signal system for single track railroads, the combination with a passing siding and associated siding track section and stretches of track extending in opposite directions from the ends of said passing siding, an entering signal and a distant signal in the rear thereof for governing train movement from one of said stretches of track into the passing siding and the associated siding track section, code transmitting means for the opposite ends of the siding track section including coding contacts operated at different code rates and normally acting to transmit driven code pulses at intervals in opposite directions over the track rails of said siding track section, and means responsive to the presence of a train in said one stretch if approaching said signals for rendering ineffective the code transmitting means providing code pulses in the opposite direction in the siding track section, and thereby permit control of said signals by the code pulses transmitted over the track rails of siding track section without interference.

18. In a coded track circuit automatic block signal system for governing the entering signals at the ends of a passing siding of a single track railroad, code transmitting means for the opposite ends of the siding track section associated with said passing siding normally governed by coding contacts operated at different code rates

to provide a beat code in the siding track section, means including a code following track relay for governing the indications of each of said entering signals, each of the stretches of single track on opposite sides of said passing siding having an end track section, and means responsive to the presence of a train in either end track section if approaching the siding for rendering ineffective the code transmitting means for the corresponding end of the siding and thereby prevent clearing of the opposing entering signal.

19. In a coded track circuit automatic block signal system for a single track railroad, the combination with a passing siding and associated siding track section and stretches of single track extending in opposite directions from the ends of said passing siding, an entering signal at each end of said siding governing train movement from the corresponding single track stretch, means including a code following track relay for governing the indications of each entering signal, code transmitting means for the opposite ends of the siding track section normally governed by coding contacts operating at different code rates to provide beat codes in said siding track section for intermittently energizing both track relays of that track section, means responsive to the cessation of the code pulses normally received at either end of said siding track section for governing the code transmitting means for that end at a code rate dependent upon the presence and location of a train in the adjacent single track stretch, means responsive to the entrance of a train into one of said single track stretches for stopping transmission of the code pulses in the opposite direction in said siding track section, and means responsive to the presence of a train in an end track section of the other single track stretch adjacent the siding and approaching the siding for stopping transmission of the code pulses in the siding track section in the other direction away from such train.

20. In a coded track circuit automatic block signal system for single track railroads, the combination with two single track stretches extending in opposite directions from the ends of a passing siding, entering signals governing train movement from the respective single track stretches into said passing siding and associated siding track section, means for governing the indications of said entering signals by code pulses transmitted over the track rails of said siding track section, code transmitting means associated with the end track section of each single track stretches adjacent said passing siding and including a series relay energized in response to the presence of a train in the corresponding end track section of that stretch, means responsive to the energization of each series relay for preventing transmission of the code pulses in the siding track section toward the opposing entering signal, and means for causing each entering signal to display a stop indication independently of the transmission of code pulses toward that signal so long as the associated series relay is deenergized.

21. In a coded track circuit automatic block signal system of the character described, two single track stretches connected by a passing siding and associated siding track section, entering signals at the ends of the respective stretches adjacent said siding for governing train movement out of that stretch, code transmitting means

for each of said ends of said stretches including a series relay energized by the presence of a train in the corresponding end track section of the stretch while that code transmitting means is operating, a directional stick relay for each of said ends of said stretches energized by train movement into the stretch at that end for rendering ineffective the corresponding code transmitting and thereby preventing energization of the corresponding series relay by such train, said stick relay being maintained energized while the corresponding end track section is occupied, and means for each end of said siding track section effective only if the corresponding series relay is not energized for transmitting driven code pulses to govern the clearing of the entering signal at the other end.

22. In a coded track circuit signaling system for governing train movement over a stretch of track including an outlying switch, a switch lock for said switch, code responsive means responsive to the transmission of code pulses in both directions toward said switch for governing the release of said switch lock, means normally acting while the stretch is not occupied by a train for transmitting such code pulses in both directions toward said switch, and means responsive to the presence of a train adjacent the switch for independently governing the release of said switch lock, whereby the switch is locked by the approach of a train in either direction but may be released for a train to enter the switch when that train is adjacent the switch.

23. In a coded track circuit signaling system for single track railroads, a stretch of single track divided into track sections and having an outlying switch associated with one of said track sections, insulated joints in said one track section adjacent the facing point side of said switch, a code following track relay connected across the track rails of said track section on each side of said insulated joints, means normally acting while the stretch is not occupied for transmitting code pulses in both directions over the track rails of said track section, a switch lock for said switch, means effective only if both of said track relays are energized by code pulses transmitted in each direction toward said switch for governing the release of said switch lock, and release means responsive to the presence of a train adjacent said switch for independently governing the release of said switch lock.

24. In a coded track circuit signaling system for a stretch of track divided into track sections and having signals at intervals governing train movement in opposite directions into and through said stretch, an outlying switch associated with one of said track sections, insulated joints in said one track section adjacent the facing point side of said switch, a switch lock for said switch, means normally acting while the stretch is not occupied for transmitting code pulses over the track rails of said track section in both directions, means responsive to the reception of code pulses in both directions on opposite sides of said insulated joints for governing the release of said switch lock, and means effective only if a train shunts the track rails adjacent said insulated joints for independently governing the release of said switch lock, whereby the switch is locked by the approach of a train in either direction until that train comes within a predetermined distance of the switch.

25. In a coded track circuit signaling system for a stretch of single track divided into track

sections and having an outlying track switch associated with one of said track sections, code transmitting means for each end of each track section including intermittently operated coding contacts and normally acting while the stretch is not occupied to transmit driven code pulses at intervals in both directions over the track rails of said track sections, a switch lock for said outlying switch, and code responsive means energized only if code pulses are being transmitted toward said switch in both directions for governing the release of said switch lock.

26. In a coded track circuit signaling system, the combination with a track section having an insulated joint in one main track at an intermediate point, polarized relay means connected to said main track around said insulated joint, means for the opposite ends of said track section normally acting to apply code pulses of the same relative polarity at different intervals to the track rails and thereby cause said relay means to operate its armature back and forth, means for controlling the transmission of code pulses in either direction toward said insulated joint, and code responsive means energized only if the armature of said relay means is intermittently operated back and forth by code pulses transmitted in both directions.

27. In a coded track circuit signaling system for railroads, the combination with a track section including an outlying track switch, means normally acting while no train is approaching said track section in either direction, for transmitting code pulses over track rails of said track section of the same relative polarity alternately in opposite directions, a switch lock for said switch, polarized relay means adjacent said switch operating an armature back and forth in response to said code pulses in opposite directions, and code responsive means energized by the movement of said armature back and forth for governing the release of said switch lock, whereby the switch may be unlocked only if no train is approaching the switch in either direction.

28. In a coded track circuit signaling system, the combination with a stretch of track having a track section including an outlying track switch, said track section having an insulated joint in one main track adjacent said switch, code transmitting means for the opposite ends of said track section normally acting while said stretch is not occupied by a train approaching the switch in either direction to transmit code pulses of the same relative polarity alternately in opposite directions toward said switch, polarized relay means connected to said one main track around said insulated joint and having an armature operated to different positions by the code pulses transmitted from the opposite ends of said track section, a switch lock for said switch, and means energized only by the intermittent operation of said armature back and forth for governing the release of said switch lock, and means including said insulated joint responsive to the presence of a train within a limited distance of said switch for independently governing the release of said switch lock.

29. In a coded track circuit signaling system for single track railroads, the combination with a stretch of track having a track section including an outlying track switch, means normally acting while said stretch is not occupied by a train approaching said switch to transmit code pulses at intervals in both directions over the

track rails of said track section toward said switch, code responsive means energized only if code pulses are received at said switch in both directions, a switch lock for said switch, a lock relay governing the release of said switch lock, an indicating lamp, manually controlled means for lighting said indicating lamp and energizing said lock relay only if said code responsive means is energized, and means responsive to the presence of a train adjacent the switch for independently governing said indicating lamp and said lock relay.

30. In a coded track circuit signaling system for single track railroads, a stretch of track having a portion of track between opposing signals, said portion of track including an outlying switch and having insulated joints forming a short release track section adjacent said switch and an approach track section on each side of said switch, a source of current and a track relay for said release track section, means normally acting while said stretch of track is not occupied by a train approaching said switch for transmitting code pulses in each approach section toward said switch, relay means for each approach track section adjacent said switch responsive to the reception of a code pulse for applying a code pulse to the other approach track section and thereby repeat the code pulses received in either direction at said switch around 35 said release track section, code responsive means energized only if code pulses are being received at both ends of said approach track sections adjacent the switch, and switch locking means for said switch governed by said code responsive means and by the track relay of said release track section.

31. In a coded track circuit signaling system for railroads, a stretch of track having a track section including an outlying track switch, code transmitting means normally acting to transmit code pulses over said track section in each direction toward said switch, means responsive to the entrance of a train into said stretch at either end for stopping transmission of code pulses in the corresponding direction in said track section toward said switch, code-responsive means adjacent said switch energized only if code pulses are being received in both directions, a switch lock for said switch, a lock relay for governing the release of said switch lock, manually operable means for energizing said lock relay only if said code-responsive means is energized, and means effective while said lock relay is energized for preventing transmission of code pulses in either direction past said switch.

32. In a coded track circuit signaling system for single track railroads, a stretch of single track divided into track sections and having signals governing train movement into and through said stretch, one of said track sections including an outlying track switch, code transmitting and receiving means associated with each end of each track section and normally acting to provide code pulses at intervals in both directions of each track section, said means acting in response to the entrance of a train into said stretch at either end to stop transmission of code pulses in each track section toward the other end, a manually operable switch lock for said outlying switch, a lock relay acting when deenergized to prevent operation of said switch lock, code-responsive means adjacent said switch energized only if code pulses are being transmitted toward said switch in both directions, means controlled by

5 said code responsive means for governing the energization of said lock relay, and means effective while said lock relay is energized or said switch lock is in its unlocked position for preventing transmission of code pulses over the track rails of said track signal past said switch in either direction.

33. In a coded track circuit signaling system for railroads, a track section having an insulated joint at an intermediate point in its length, code transmitting means for the opposite ends of said track section including coding contacts intermittently operated at different code rates for normally applying code pulses at intervals to the track rails at both ends of said track section, and means including a source of current and a code following track relay associated with said track section at each side of said insulated joint for intermittently energizing the track rails on the opposite side of said insulated joint in response to the energization of said track relay by code pulses transmitted from a corresponding end of said track section.

34. In a coded track circuit signaling system providing approach control for highway crossing signals, a stretch of railway track including two sections at the point of intersection of the railroad with a highway, a crossing signal associated with the highway crossing, means for transmitting driven code impulses of predetermined code rates over the rails of said sections for controlling the indications of signals governing traffic in opposite directions over said stretch, two shunt track relays at the highway crossing each connected across the rails of its respective track section and responsive to the presence of driven code impulses in either direction in that track section, an interlocking relay having two windings each respectively controlled by one of said shunt track relays in a manner to be deenergized when the shunt track relay for that winding ceases to receive driven code impulses and the initially deenergized winding acting to cause the operation of said crossing signal only so long as it remains deenergized regardless of the condition of deenergization of the other winding if contemporaneously deenergized, and code transmitting means for the highway crossing end of each section for applying driven code impulses of a character distinctive from said impulses of predetermined code rates to the track rails of that section when the other section is occupied by a train receding from the highway crossing to thereby cause the re-energization of the initially deenergized winding of the interlocking relay irrespective of the direction of train movement past the highway crossing.

35. In a coded track circuit signaling system providing approach control for highway crossing signals, a stretch of railway track having signals governing the entrance of traffic into said stretch in both directions, said stretch being divided into at least two track sections one on each side of a highway crossing, a crossing signal, driven code transmitting means associated with each of said signals for applying impulses of certain code rates for controlling said signal at the opposite end, decoding means associated with each signal for governing the indications of such signal only in response to said driven codes of said certain rates received from the opposite end of said stretch, a shunt track relay at said highway crossing for each of said sections responsive to the presence of code impulses in either direction

in said track section for normally preventing operation of the crossing signal but permitting operation of the crossing signal when shunted by a train approaching the crossing and code transmitting means at said highway crossing end of each section for applying driven code impulses of a code rate distinctive from said certain code rates to the track rails of that section when the other section is occupied by a train receding from the highway crossing to thereby reenergize the shunt track relay for such other section just vacated by the train, whereby the crossing signal may be caused to cease its operation when a train has passed the highway intersection in either direction without causing the clearing of the signal in the rear of such train.

36. In a coded track circuit signaling system for a stretch of single track including a plurality of track sections, two of said track sections constituting approach track sections on opposite sides of a highway crossing, a signal at each end of the stretch governing train movement into the stretch, code transmitting means and code receiving means for each of said track sections normally cooperating to transmit code pulses at intervals in both directions over the track rails of each track section dependent upon the reception of code pulses at the adjoining end of the adjacent track section, a shunt track relay for each of said approach track sections on opposite sides of said highway crossing, each shunt track relay being connected across the track rails and energized by code pulses applied at either end of the associated track section unless shunted by the presence of a train in that track section, a protective device for said highway crossing, and means including said shunt relays for governing the operation of said protective device.

37. In a coded track signaling system for a stretch of single track divided into a plurality of track sections and having signals at intervals governing train movement in opposite directions, two of said track sections constituting approach track sections one on each side of a highway crossing, code sending means and code receiving means for each end of each track section normally cooperating to send current pulses at intervals in both directions over the track rails of said track sections, each of said code receiving means except those for the ends of said stretch acting when deenergized to render ineffective the code sending means for the adjoining end of the adjacent track section, a shunt track relay connected across the track rails of each of said approach track sections at the highway crossing and energized by current pulses applied at either end of that approach track section until shunted by the presence of a train in that track section, a protective device for said highway crossing, and means including said shunt track relays for governing the operation of said protective device.

38. In a coded track circuit signaling system for a stretch of track including an approach track section for a highway crossing, code transmitting means including intermittently operated coding contacts for each end of said track sec-

tion normally operating to send code pulses at intervals in both directions over the track rails of said track section, means governed by the presence of a train in said stretch moved toward said

5 approach track section for stopping transmission of current pulses in said approach track section in a direction away from such train, and means including a shunt track relay connected across the track rails of said approach track section at 10 one end and energized by current pulses applied at either end of said track section for detecting when such approaching train enters said approach track section.

39. In a coded track circuit signaling system for a stretch of single track including two approach track sections one on each side of a highway crossing, opposing signals governing train movement in opposite direction into said stretch, coding means at said crossing for each of said 15 approach track sections for applying signal control code pulses to the track rails of that track section dependent upon the reception of code pulses at the adjoining end of the other track section, thereby governing the indications of said signals, a shunt track relay connected across the track rails of each of said track sections at said 20 crossing and energized by potentials applied at either end of the associated track section unless shunted by the presence of a train, a protective device for said highway crossing, means including said shunt track relays for governing the operation of said protective device, and means effective if either of said approach track sections is occupied by a train receding from the crossing for governing the coding means for the other track section to give an energization different from said signal control code pulses and thereby energizes the associated shunt track relay without clearing the signal in the rear of such train.

40. In a coded track circuit signaling system for a stretch of single track divided into a plurality of track sections and having signaling at intervals governing train movement in opposite directions into and through said stretch, said 25 stretch being intercepted by a highway crossing at the adjoining ends of two approach track sections, coding means for each end of each track section operable to transmit signal control code pulses toward the opposite end, each of said coding means except those for the ends of said stretch being governed by the reception of code pulses at the adjoining end of the adjacent track section, a shunt track relay connected across the track rails of each of said approach track sections adjacent said crossing and responsive to an energizing potential at either end of the associated track section unless shunted by a train, a protective device for said highway crossing governed jointly by said shunt track relays, and means effective while either of said approach track sections is occupied by a train for energizing track rails of the approach track section in the rear of such train distinctively from a signal control code to cause energization of the associated shunt track relay without clearing the signal next in the rear of such train.

NEIL D. PRESTON.

DISCLAIMER

2,350,639.—*Neil D. Preston*, Rochester, N. Y. CODED TRACK CIRCUIT SIGNALING SYSTEM. Patent dated June 6, 1944. Disclaimer filed December 22, 1945, by the assignee, *General Railway Signal Company*.

Hereby disclaims from claim 22, any system of coded track circuits except wherein there is an outlying track switch in a stretch of track with code transmitting means normally acting at all times while the stretch is not occupied by a train, and without having its operation initiated and discontinued by any supervisory manual control, for transmitting code pulses in both directions toward such outlying track switch.
